UNITED STATES PATENT OFFICE.

WILLIAM L. WARD, EMILE C. BOERNER, AND HERBERT D. REMSEN, OF PORT CHESTER,
NEW YORK, ASSIGNEES TO RUSSELL, BURDSALL & WARD BOLT AND NUT CO., OF
PORT CHESTER, NEW YORK, A CORPORATION OF NEW YORK.

DOUBLE-ACTING AUTOMATIC NUT-BLANK MACHINE.

1,088,192.

Specification of Letters Patent. Patented Feb. 24, 1914.

Application filed June 27, 1910. Serial No. 569,053.

To all whom it may concern:

Be it known that we, WILLIAM L. WARD, EMILE C. BOERNER, and HERBERT D. REMSEN, residing at Port Chester, in the county of Westchester and State of New York, have invented certain new and useful Improvements in Double-Acting Automatic Nut-Blank Machines, of which the following is a full, clear, and exact description, such as will enable others skilled in the art to which it appertains to make and use the same.

This invention relates to means instrumental in the production of nut-blanks from stock-bars, but inasmuch as certain noteworthy characteristics of the invention prominently appear in its illustrated concrete form as a compact and unitary mechanism capable of receiving a stock-bar at one point and delivering high-grade nut-blanks at another point, it will be conducive to clearness to specifically disclose the same through such an embodiment thereof.

As introductory to a more detailed discussion of the essentially novel features, arrangements and combination underlying the commercial utility of this apparatus, it may be preliminarily noted that, for various reasons known to those skilled in this art, it is desirable to produce nut-blanks from commercially available stock-bars of an inexpensive character by operations effected under normal temperatures and without the necessity of shaping the material while in a highly heated condition. The rapid production of high-grade hexagonal nut-blanks from such an ordinary stock-bar by means of an essentially automatic unitary apparatus, as free as possible from delicate, involved or awkwardly related parts or sub-mechanisms, and requiring but little attention, has been the goal for which those commercially engaged in the art of making nuts have long striven.

Now this invention has in contemplation the production of an automatic unitary apparatus which, although necessarily somewhat complex and intricate in appearance, nevertheless displays the greatest simplicity, convenience, serviceability and compactness commensurate with the rapidity of the op-

erations automatically performed by the same, and the comparatively slight amount of personal attention required during the use thereof.

55

A further object is to render available at a relatively moderate cost a mechanism embodying a structure such that the various parts may move and operate to the best advantage so as not only to reduce the number 60 of parts, but also to eliminate, so far as is possible, any unproductive motions of such parts. For example, it is proposed to combine in this mechanism a reciprocating structure which, during a forward movement, so 65 to speak, will sever and partly form nut-blanks from a stock-bar, and during the return movement will operate to crown and otherwise finish the parts.

Another object of this invention is to embody in the unitary machine various feeding and conveying mechanisms, each combined in an essentially novel manner with one another and with other elements of the machine, and each to a greater or less extent 75 individually presenting noteworthy characteristics or features of novelty.

A more specific object of this invention is to so construct the mechanism for initially feeding in the stock-bar that the same 80 will not only positively and accurately operate, but also so that it will be a simple matter for the operator to disengage the stock-bar whenever, by chance, the mechanism should operate imperfectly or when it is desirable to make a hand adjustment, as at the time a new bar is being introduced into the machine.

Another object is to so devise the stock-bar feeder that damaged parts may be 90 readily replaced and adjustments may be made for wear, and to so construct the same that, in case the progress of the stock-bar is obstructed and the feed thereof thus prevented, the feeder will not be damaged 95 but merely a readily replaceable safety pin will be sheared.

It is also an object of this invention to employ a horizontally reciprocating vise mechanism for feeding the stock-bar and to 100 so arrange and construct a lever for driving the same that the intermediate pivot or ful-

crum thereof may be adjustably positioned to vary the stroke of the lever, and also enable the pivotal connection between the lever and the sliding vise mechanism to be 5 adjusted as desired.

Another object is to provide a bar-centering mechanism capable of acting as an intermediary between the stock-bar feeder and the punches, so as to automatically position 10 the stock-bar accurately with reference to the punches and die apertures.

It is also an object of this invention to so devise, construct and arrange the bar-centering mechanism that it will be compactly 15 positioned in the combined machine and will not interfere with or impede the action of the other elements with which it is closely associated.

A still further object is to render available 20 an automatic bar-centering mechanism of a simple and durable character and capable of being very readily adjusted.

A further object of this invention is to devise and embody in the machine a mechanism 25 for successively receiving roughly formed nut-blanks at one portion of the machine and transporting said blanks in the form of a train to another portion of the machine, and then successively removing 30 individual nut-blanks from the forward end of the train in such manner as to insure precision and regularity of operation irrespective of the ordinary variations in length of the train of blanks.

35 A further object is to devise a blank-handling mechanism capable of various applications and which will operate on a multiplicity of more or less irregularly disposed blanks, and will deliver such blanks so as 40 to be accurately located in any predetermined position.

Another object is to so arrange and construct the heavy working parts of this machine, such as the reciprocating head which 45 carries the punches, that both the forward and return reciprocations of the same may be directly utilized in performing work, and thus not only enhance compactness in the machine, but also utilize the full working 50 stroke of the reciprocating head, and to do so by arranging the punches at each end thereof so that during the advance one set of punches will operate and during the retreat the second, or finishing set of punches 55 will come into play.

Another object is to combine with this double-acting punch-carrying head a roulette mechanism capable of efficiently presenting nut-blanks to the appropriate punches during the stages of finishing thereof.

A further object of this invention is to 60 so construct and arrange the parts that the blanks will be accurately positioned and so that in case any undue irregularity should 65 occur in the operation of the machine, the

same may be automatically stopped and prevent damage.

Other objects and advantages will be in part pointed out hereinafter and in part rendered apparent by means of the accompanying illustrations.

The invention accordingly consists in the features of construction, combinations of elements and arrangement of parts which will be exemplified in the construction hereinafter set forth, and the scope of the application of which will be indicated in the following claims.

To promote a full understanding as to the manner in which this invention may be carried out, drawings exemplifying a preferred embodiment have been appended as a part of this disclosure, and in such drawings like characters of reference denote corresponding parts throughout the several views, of which—

Figure 1 is a plan view of one corner of the unitary machine showing in detail the construction and arrangement of the stock-bar feeder; Fig. 2 is a side elevation of the stock-bar feeder looking in the direction of the movement of the stock-bar as it is fed into the machine, as indicated by the arrow on said bar shown in Fig. 1; Fig. 3 is an end elevation showing the cam and rocker mechanism from which motion is primarily derived and by means of suitable mechanism transmitted to the centering mechanism; Fig. 4 is a side elevation showing further details of the cam and rocker mechanism illustrated in Fig. 3; Fig. 5 is an end elevation of the combined machine showing the two rockers on the right and left hand sides of the machine, respectively, which form parts of the mechanism for centering the stock-bar; Fig. 6 is a side elevation of the combined machine illustrating more especially certain details of the rocker 82 shown at the right hand end of Fig. 5; Fig. 7 is a detailed view with certain parts broken away, illustrating the construction of the centering tongs and the manner in which they coöperate with the centering cam; Fig. 8 is a section taken along line 8—8 of Fig. 7, showing the construction of the wedge-shaped grooved centering cam and the manner in which it coöperates with the centering tongs; Fig. 9 is a side elevation partly in section, of the centering mechanism arranged in conjunction with certain features of the combined machine, showing more particularly the direction of feed of the stock-bar and the manner in which the same is centered adjacent the point at which it is punched and successively sheared into roughly formed nut-blanks; Fig. 10 is a top plan view of the mechanism illustrated in Fig. 9, showing certain details not clearly apparent from the latter figure; Fig. 11 is a side elevation looking in the direction of

the axis of the stripper actuating-shaft 118, which is mounted at the forward end of the machine. This figure shows a portion only of the mechanism employed for the purpose 5 of clamping the stock-bar during the advance of the punches, and also for the purpose of subsequently assisting in stripping from the punch during its retreat so much of the stock as may adhere to the same; Fig. 10 10 shows another more remote portion of the mechanism shown by Fig. 11, and illustrates, in part, the cam mechanism whereby the reciprocating rod 117 derives its motion from the main shaft, and also shows the 15 clutch mechanism and the hand-operated means for disengaging the same, as well as an automatic mechanism for the same purpose, whereby the operation of the machine may be quickly stopped as required by any 20 exigency; Fig. 13 is a side elevation, shown partly in section, of the mechanism set forth in Fig. 12; Fig. 14 is a view somewhat similar to Fig. 10, but showing certain features added and others eliminated for the 25 purpose of disclosing more clearly the preferred manner of mounting the dies and parts associated therewith, adapted to first form an aperture adjacent the end of the stock-bar, and then shear off a section with 30 the aperture centrally located therein, thus forming a rough nut-blank ready for the subsequent operation of trimming; Fig. 15 is a face view of the features shown by Fig. 14; Fig. 16 is a detail in section showing the 35 manner in which the trimming dies are arranged whereby a train of nut-blanks may be forced through the same and thus undergo a series of trimming operations; Fig. 17 is a plan view showing the delivery end of 40 the conveyer for the nut-blanks and the transfer mechanism for picking nut-blanks from the end of such conveyer and transporting the same to the roulette which carries the blanks through the successive operations 45 of repunching, crowning, retrimming, etc.; Fig. 18 is a detail view of the spring finger or picker forming an element of the transfer mechanism and which comprises two spring arms or tongs adapted to 50 be advanced to spring over and frictionally take hold of a nut-blank located at the extremity of the conveyer 238, then withdraw the same from such conveyer, and ultimately position the same between vertically movable 55 fingers which carry the nut-blank to the roulette; Fig. 19 is a rear end elevation of the picker shown by Fig. 18; Fig. 20 is an elevation of the transfer mechanism as viewed from the end of the nut-blank conveyer, looking in the direction of travel of the nut-blanks, *i.e.*, toward the rear end of the machine; Fig. 21 is a side elevation, showing in part certain of the unobstructed 60 elements of Figs. 17 to 20 inclusive, and disclosing more particularly the arrange- 65

ment of the cams, levers and other elements which operate the transfer mechanism: Fig. 22 is an end elevation looking forwardly in the direction of the axis of the cam shaft 251 and showing more particularly the lever which actuates the vertically moving tong mechanism, as well as the levers which operate the plungers for transferring the blanks from the horizontally moving tong mechanism to the vertically moving tong mechanism and for transferring them from the latter to the roulette, which carries them through subsequent operations; Fig. 23 is an end elevation showing the details of construction of the roulette, *i.e.*, the means instrumental in carrying the nut-blanks through the several positions wherein they undergo operation; Fig. 24 is a longitudinal vertical section showing further details of construction of the roulette, together with the arrangement of the shaft for rotating the same, and illustrating also certain of the dies in the stationary frame and the punches coacting therewith carried by the double-end reciprocating head; Fig. 25 is a vertical section taken through the crowning die, showing in detail the ejector mechanism therefor; Fig. 26 is a fragmentary end elevation of the rear of the ejector mechanism shown by Fig. 25; Fig. 27 is an end elevation looking at the rear of the machine and showing further details of the ejector mechanism for the crowning die, also the rotating mechanism for the roulette, as well as the stop mechanism for the entire machine; Fig. 28 is a side elevation of the mechanism shown by Fig. 27 looking at the right-hand side; Fig. 29 is an elevation looking in the same direction with various parts eliminated, showing more especially the construction of the locking device for preventing rotation of the roulette in the direction of its travel; Fig. 30 is a vertical transverse section taken through the entire machine, showing more especially the features of construction of the double-acting reciprocating head which carries the punches and the discharge mechanism for the scrap resulting from the various operations; Fig. 31 is a longitudinal vertical section showing further details of the double-acting header and other parts associated therewith; Fig. 32 is an elevation of certain parts of the automatic safety-stop mechanism; Fig. 33 is a view of the same mechanism, looking at the same in a transverse direction; Fig. 34 is a vertical sectional detail showing more clearly the construction of the adjustable pivot for the swinging lever 48 of the feed mechanism. Fig. 35 is a plan view partly in section, showing further details of the same. Fig. 36 illustrates a conventional form of stop mechanism for the main driving shaft. Fig. 37 is a view in elevation of the pin of said stop mechanism. Fig. 38 illustrates in cross sec- 130

tion the position assumed by the parts of said stop mechanism when operating to drive the machine. Fig. 39 is a similar view showing the stop mechanism in operative relation. Fig. 40 is a general assembly of the entire machine shown in plan.

Continuing now by way of a more detailed description of the herein disclosed machine, it will be conducive to clearness to trace the progress of the stock or material undergoing treatment through the machine and successively describe in detail the various mechanisms and elements which carry such material from one place to another, and from time to time carry out the various operations thereon.

The nature of this machine naturally requires the consumption of considerable power in the form of heavy pressures, and therefore mechanism will ordinarily be employed to gear down the speed of the main counter-shaft in the factory in which it is employed. To that end, 1 illustrates a pulley which will be driven in the direction indicated by the arrow A, and the power applied to this pulley will be geared down to drive the main driving gear 5 in the direction indicated by the arrow B by means of the intermediate gears and spurs 2, 3 and 4, or the like. The main driving gear 5 will be strongly constructed and is connected by means of a clutch or stop mechanism shown in detail by Figs. 34 to 39 inclusive with the main driving shaft 6 which passes through the body of the machine, as illustrated by Figs. 30 and 40, and splined to its protruding end is the duplex cam 7. This cam provides a circumferential cam groove 8 and an end or face groove 9. The end groove 9 operates with certain mechanisms, which will be forthwith described, to enable the infeeding stock-bar to be tightly gripped at appropriate intervals; while the former cam groove 8 co-operates with other means for intermittently feeding or translating the bar into the machine through predetermined distances when said bar is gripped, and also for returning the mechanism to obtain a fresh grip for the next advance.

The stock-bar feeder consists, as has been above stated, of a gripping means in the nature of a vise and a translating means for reciprocating such vise. The gripping means comprises a rock lever having an actuating end 14 and an actuated end 10, which latter carries a roller riding within the cam groove 9, as appears more clearly from Figs. 1 and 2. As the shaft 6 turns in the direction indicated by the arrow B, the actuated end 10 rocks up and down, and this produces a corresponding movement in the actuating end 14. This lever is pivoted at an intermediate point by means of a pivot bolt 11, which is supported at its outer end by means of an uprising plate 12, which latter plate is

bolted to lugs 13 which extend from the main frame of the machine. Mounted on the extremity of the arm 14 of the rocker lever is the toe or bearing piece 15 designed to actuate the cam controlling the bar gripping mechanism. This toe is detachably secured in place, as by means of bolts, so as to enable it to be replaced if unduly worn or injured. As shown, this toe projects through a suitable aperture, indicated by dotted line 26, in a stationary bearing block 25, along which bearing block slides the main piece 20, the top plate 21 and the bottom plate 22 of the bar-feeding mechanism. This aperture, indicated by dotted line 26, is slightly wider than the toe 15, but is considerably higher, so as to enable the toe 15 to travel vertically up and down during the operation of the gripping mechanism. The toe 15 passes through the stationary bearing block 25 and enters a horizontally elongated recess, indicated by dotted line 27 (see Fig. 2), in a sliding block 20 forming a main part of the feeding mechanism. Inasmuch as this block 20 must be capable of reciprocating or translating horizontally a distance equal to that of the feed of the stock-bar, the recess indicated by dotted line 27 will be sufficiently long horizontally to avoid interference with the rounded extremity 16 of the toe 15. This extremity 16 resembles in shape a wide gear tooth and closely interfits within an open channel horizontally formed in a vertically reciprocating cam or bearing block 17. This cam is carried by the block 20 and is capable of moving up and down, as indicated by the arrow D, independently of the position of the block 20; but on the other hand it is positively carried in a horizontal direction along with said block 20. To that end, the cam 17 provides on either side an elongated guide or gib 18 which secures the cam 17 to the block 20, and yet enables it to freely rise and fall, *i. e.*, slide up and down therein. The cam 17 is relatively narrow, and to enable its engagement with the gearlike extremity 16 of the toe 15 to be maintained, such extremity 16 is fully equal in width to the distance through which the stock-bar is fed.

It may here be stated that the recess indicated by dotted lines in the sliding or translating block 20 necessarily exceeds in height the distance through which the cam 17 is reciprocated by means of the toe 15.

The cam portion of the vertically reciprocating cam 17 is indicated by 19 and co-operates with a roller 32 indirectly carried by a swinging massive arm 30. The block 20, as has been stated, reciprocates horizontally and is slidably supported on the guide or bearing block 25. To that end, upper and lower cap plates 21 and 22 are securely bolted to the block 20 by means of bolts 23 and 24, so that these three pieces reciprocate

as a unit. Means are provided for taking up and adjusting wear, as clearly appears from Fig. 2.

Extending from the block 20 are two lugs 28, in which is journaled the lever pin 29, which in turn supports the massive swinging arm 30 so as to enable the latter to have a limited angular movement, as indicated by the arrow E. This movement is utilized 10 in gripping the stock-bar and is produced through the instrumentality of the cam 17 and the parts which will now be described.

A block 31 is mounted in a counterpart recess in the lower end of the massive swinging arm 30 and has a certain amount of possible play which is permitted on the one hand by a spring and limited on the other hand by a suitable adjustable stop, preventing the same from protruding too far under 15 the influence of such spring. This part 31 carries the roller 32 which coacts with the cam 19, and 34 indicates the spring which is housed within a suitable recess 33 and is capable of being adjusted as to tension by 20 means of the cap screw 35. A stem 36 extends from the part 31 and passes freely through the cap screw 35 and is provided externally with a pair of lock-nuts 37 so that the outward movement of the part 31 25 may be positively limited, while the inward movement which necessarily more or less varies in extent, due to irregularities in the stock-bar, is taken care of by the powerful spring 34. From this it will be perceived 30 that when the cam 17 is depressed by means of the toe 15, the roller 32 rides up the cam incline 19 and through the pressure of the spring 34 urges the lower end of the member 30 outwardly, and correspondingly 35 urges the upper end of such part 30 in the opposite or inward direction. It is this latter end that is utilized in gripping the stock-bar. The upper end of the arm 30 provides two integral lugs 38 and 39, which are 40 spaced apart, as shown. Quite snugly, yet slidably fitting within a recess in the lug 39, is a vise-block 41, which is preferably backed by means of a block 42, which in turn is positively positioned by means of the hub 43 of the hand-lever 44. The block 42 and the hub 43 provide counterpart cams in their adjacent faces, which cams are clearly illustrated by Figs. 1 and 2 and are so constructed that when the hand-lever 44 is 45 swung down so as to rest on the horizontal rest 45, the block 42 will be crowded outwardly, whereas when the arm 44 is moved through 90 degrees, the block 42 may be drawn back somewhat by means of the shaft 46 and the spring 47, thereby easing up the pressure between the vise-block 41 and the stock-bar. An immovable vise-jaw 40 is detachably secured to the top plate 21 in some suitable manner, such as by setting the 50 same in a recess in the top plate 21. By

this instrumentality, should it be desired to stop the feeding of the stock-bar temporarily without stopping the entire machine, or should it be desired to adjust the extent of entry of the stock-bar in the machine (as when a new bar is required), the operator, by lifting the handle 44, can release the vise-jaws from the stock-bar, irrespective of the position of the feeding mechanism, and thereupon the freed stock-bar can be manually adjusted in position. Upon turning the handle 44 to its normal position, the machine will be ready to resume its cycle of operations.

The feeding means for horizontally reciprocating the vise-bearing top plate 21 will now be described. It may here be noticed that it is highly desirable to so construct and arrange the elements controlling the reciprocations of the stock-bar vise, as to enable adjustments to be easily made whereby the extent and periodicity of the automatic feed may be regulated and accurately determined. To that end, this invention proposes a multi-part lever 48, which at one end carries the roller 49 which coacts with the circumferential cam 8. This lever is pivotally supported at an intermediate point and has its free end, so to speak, connected with the top plate 21 of the feeding structure. The 55 relation between these three points will determine the character of the feed and therefore means have been adopted to enable this relation to be varied within reasonable limits. Thus, the bolt 50 constitutes the intermediate pivot of the lever 48, but this bolt is so arranged and constructed as to be capable of being secured in various positions.

This construction is very clearly shown in Figs. 1, 2, 34 and 35, from which it will be seen that the lower end of the bolt passes through a shelf-like portion 13' extending from the main frame of the machine. This portion 13' is provided with a rectangular recess (see Fig. 34) into which is fitted the block 50'' and below this block is located the slot 55' through which the shank of the bolt 50 passes. A nut 50' serves to lock the bolt and block in position against movement. For the purpose of facilitating adjustment, the adjusting bolt 50''' is provided and said bolt is rotatably mounted in the frame portion 13' and has a screw-threaded shank in engagement with the block 50'', so that by turning the bolt said block may be shifted 100 in position. The upper end of the bolt 50 passes through a detachable lug 51 which is in turn adjustably secured to the main frame by means of bolts 52 passing through suitable slots shown more clearly by Fig. 1. In 105 this way the position of the bolt 50 with respect to the main frame may be varied at will. The lever 48 is also adjustably mounted in the saddle-block 53 by means of bolts 54 which are adapted either directly or 110

through the instrumentality of an insert-piece, to clamp the snugly fitting part 55 of the lever 48 in a corresponding aperture in such block 53. It is to be understood that 5 the pivot bolt 50 has its bearing directly on the swinging block 53 and passes through the elongated aperture, indicated by dotted lines 55' in Fig. 1. From this, it will be 10 readily understood that the exact position 10 of the pivot bolt 50 may be very readily secured.

At this point attention is directed to a safety appliance employed in connection with the feed mechanism. It may occasionally 15 happen that either because of a failure to sufficiently clear away the metal cut from the forward end of the stock-bar, or for other reasons, the forward progress of the stock-bar will be unduly or even positively 20 obstructed, and to prevent the feeding mechanism from being damaged or fractured by reason of its inability to advance the stock-bar, this invention contemplates so constructing the lever 48 that a suitably positioned safety pin, amply strong for all ordinary 25 purposes, will be sheared and thus prevent rupture of this lever or other element of the feed mechanism. To that end, the forward or actuating end of the lever 48 terminates somewhat short and extends in 30 the form of the extension piece 56, which is pivoted to the same by means of a strong bolt 57. A clamping block 58 which engages a circular lip 59 which is integral with the forward end of the lever, also assists in 35 positioning these parts. Adjacent the extremity of the forward end, is an aperture 49' which enlarges toward the under surface of such part and is in registry with the corresponding 40 aperture in the extension piece 56. A safety pin 49" fits in and is retained by these aligned apertures, so that in case the pressure becomes at any time excessive, this pin may be readily sheared and may then be 45 replaced by a duplicate part. This invention also embodies means for adjusting the relative position of a pivot bolt 60 which is directly instrumental in connecting the sliding vise-block 21 with the actuating lever. 50 The extension piece 56 is provided with a square recess adjacent its end, within which is adjustably positioned a block 62 which is clamped in place by means of the nut 61 on the pivot bolt 60. It will from this be 55 readily perceived that it is a very simple matter to so adjust the lever 48 as to feed the vise-block 21 and its associated parts through any desired feed spacing.

The operation of the stock-bar feed 60 mechanism will be obvious from the foregoing, but may be briefly recapitulated as follows: Assuming the parts to be in the position shown by Fig. 1, in which the stock-bar feeder is in the advanced position, the

further rotation of the main shaft 6 will 65 raise the lever end 14, thus uplifting the cam 19 and permitting the arm 30 to swing back to ease up the clamping pressure on the stock-bar. The circumferential cam 8 is so designed that the roller 49 will now be 70 caused to move toward the frame of the machine so as to swing the other end of the lever 48 in the opposite direction and thereby move the released gripping vise along the stock bar a distance corresponding to the 75 length of a blank. During this withdrawal of the vise the stock-bar is not moved, but at the end of the backward stroke the cam 9 operates on the lever arm 10 to actuate the part 18 and thus cause the cam 19 to outwardly move the roller 32 and swing the arm 30 into a position adapted to grip the stock-bar. Thereupon the circumferential cam 8 acts on the roller 49 to swing the lever 80 48 in a direction such that the vise will be advanced as indicated by the upper head of the arrow C, and thus feed the stock-bar into the machine a distance corresponding to the length of a nut-blank. This brings the end of the stock-bar opposite the shearing-off punch 1' (Fig. 40) so that as the latter now advances a nut-blank will be 85 sheared from the end of the stock-bar. It will be noticed that this shearing-off punch extends forwardly some little distance beyond the forward extremity of the perforating punch 2' (Fig. 40) so that the shearing-off punch will perform its function just before the perforating punch operates. When the perforating punch advances to perforate the stock-bar near its end, it may be 90 observed that the stock-bar is deformed and elongated through the action of the perforating punch to an extent sufficient to cause the end of the stock-bar to bind unduly against the shearing-off punch during the withdrawal of the latter. It will be understood that the shank of the shearing-off punch is slightly undercut and that this binding action would take place near its 95 head. To prevent this action, however, this invention proposes a construction whereby the stock-bar is retracted a slight distance just after the perforating punch has been 100 withdrawn, thereby affording a free withdrawal of the shearing punch. This is accomplished by providing the circumferential cam 8 with a slight undercut 8' so that the roller 49 will be given a slight movement 105 toward the frame of the machine just after the perforating punch has been withdrawn, thereby effecting a slight retraction of the stock-bar during the withdrawal of the 110 shearing-off punch.

The bar-centering mechanism.—The purpose 115 of this mechanism is to insure that the stock-bar, when fed into operative relation with the punches and dies, will be in suit-

able registry with the same, so that deformed nut-blanks may not result from an imperfect positioning of the stock-bar.

To fully appreciate the usefulness of a bar-centering mechanism, it may be recalled that commercial stock-bars are necessarily more or less warped or irregular in shape, and therefore an ordinary channel or feed-way would not alone suffice to insure absolute registry of the stock-bar over the shearing and cutting dies. Furthermore, it will be understood that during the shearing and cutting of the stock-bar, fins and other slight irregularities are quite commonly produced, and this also is another cause of irregularity. This invention proposes to obviate this difficulty by employing a pair of oppositely positioned centering fingers which grip the opposite sides of the stock-bar at a point closely adjacent the punch, so that the end portion of the stock-bar about to be operated on will be accurately and positively positioned, irrespective of any warping or twisting that may occur in the more remote portions of the bar. This mechanism may now be specifically described.

Turning now to Fig. 3, 70 denotes a cam shaft mounted above the main frame near and parallel with one side thereof. This cam shaft is continuously driven, as indicated by arrow G, by means of the beveled gear 71 in mesh with a right angled beveled gear 72 secured to the supplementary upper shaft 72 which, by means of a suitable mechanism, is driven by the main drive shaft 6, rotating as indicated by arrow F. At its other end, the shaft 70 carries a suitable cam 73, which is shown in larger detail by Figs. 3 and 4 and turns as indicated by arrow H. A bearing-block 77 is bolted or otherwise suitably secured to the main frame of the machine and this bracket 77 carries a pivot pin 76 which is suitably retained in place by means of nuts in the ordinary manner. A rocker is pivoted at an intermediate point to this bearing bolt 76 and the upper end 75 of the rocker carries a roller 74 which rides in contact with the periphery of the cam 73 and derives a rocking motion therefrom. This rocking motion is reproduced and reversed in direction at the lower extremity of the arm 78 of this lever, and by means of a suitable connecting bolt 80 is transmitted, as shown by arrow I, to the long rod 79 which passes (parallel with the stock-bar feed) from one side of the combined machine to the other, where it is connected by means of a bolt 81 with a second rocker 82. This is shown clearly by Fig. 5. Through the above described mechanism, the rocker 82 will be periodically actuated to interpose a centering cam between the ends of centering tongs, which at their other ends operate to bring the stock-bar

precisely into the desired position. The manner in which this is done will presently appear. The rocker 82 is pivotally positioned at its center by means of a pivot bolt 83 which is in turn mounted in a suitable stationary bearing-block or bracket 84 secured to the side of the main frame of the machine. At its upper end, the rocker 82 is pivoted to a vertically sliding block 86 by means of a pivot bolt 85. This sliding bearing block 86 slides up and down (for the limited distance required to correct for the slight rise and fall of the upper end of the rocker 82), in a suitable bearing recess in the end 87 of the centering cam 88, thereby translating such cam, as indicated by the arrow K. The detailed construction of this cam is shown somewhat more clearly by Figs. 7 and 9. It comprises two end bearing portions 88 and 90 which have a sliding bearing in suitable slideways 91 and 92 provided by the main frame of the machine and illustrated by dotted lines in Fig. 9. The intermediate portion 89 of the centering cam is wedge-shaped and its upper and lower inclined contact faces are grooved, as illustrated more clearly by Fig. 8, so as to form suitable raceways for the contact fingers of the centering tongs. As shown by Fig. 8, these raceways or tracks are preferably grooved, as indicated by 93, and the contacting tips of the actuated fingers of the tongs have a counterpart formation. The tongs are shown more clearly in Figs. 7, 9 and 10, and consist of two swinging arms 94 and 95. The upper arm 94 is, by means of a pivot bolt 96, supported at an intermediate point by a standard 97 projecting from the frame of the machine, and the other centering arm 95 is in like manner pivoted to a bolt 98, also secured to a suitable part of the main frame of the machine. The outer ends of the pivot bolts 96 and 98 are preferably secured together by means of a short heavy distance link 99, which is adapted to maintain the outer ends of the bolts in parallelism and prevent bending or displacement of said bolts under the stresses of the centering mechanism. At its actuated end, the centering arm 94 carries the finger 100, which finger has a screw threaded shank 101 and is screw threaded through an aperture in the arm 94 and securely retained in place in a predetermined position by means of a lock-nut 102. This arrangement enables the operator to readily set the finger 101 so as to accurately locate the arm 94 within suitable limits. At its forward end, this arm 94 detachably carries the centering finger 103, which is secured in place in any suitable manner, as by a block 104, which preferably is dovetailed on the end of the arm 94 so as to enable the centering finger 103 to be shifted transversely. The companion arm 95 of the centering device also carries an 130

actuating cam finger 105, which is retained in place by means of a nut 106, and at its forward end also carries a centering finger 107 secured in the corresponding end of the arm 95 by means of a nut 108.

When the cam 73 rotates, the various parts above described will be operated, resulting in a reciprocation of the centering cam 88 and producing a scissors-like movement of the levers 94 and 95, thereby causing the centering fingers 103 and 107 to approach; as indicated by arrows L in the predetermined manner always equidistant from the center line of the stock-bar, and thus cause the stock-bar which is gripped therebetween to be centered and brought into the desired precise registry with the punches and apertures.

Stock-bar punching clamp and stripper.— This mechanism has a two-fold function, *i. e.*, first, to clamp the stock-bar tightly in place at the instant of punching so as to prevent any displacement under the forcible action of the punches; and second, to enable the punch to be wholly withdrawn from the newly formed aperture in the stock-bar and thus entirely release the same from any engagement or sticking together due to fins or irregularities produced by the punch; whereby the feed may be continued. This mechanism is shown more clearly by Figs. 5, 9, 10, 11, 12, 13 and 34. The source of power for this mechanism is also derived directly from the main shaft 6, which carries the cam 110 (shown best in Figs. 5, 12 and 13) which rotates in the direction indicated by the arrow B. A rocker arm 111 is pivoted at the side of the frame of the machine adjacent this cam by means of the pivot bolt 112, and the upper end of this rocker arm 111 carries a roller 113 which rolls in contact with the periphery of the cam 110 during the rotation of the main shaft 6 and thus imparts a corresponding oscillation to the rocker arm 111. The lower end of this rocker arm terminates in the form of a yoke 114, which carries a pivot pin 115 passing through the appropriately shaped end 116 of the elongated rod 117. This rod 117, therefore, has a limited reciprocation, as indicated by the arrow M, and as appears more clearly from Fig. 40 this rod 117 extends along the side of the machine to the end of a transversely extending shaft 118, shown in plan view by Fig. 40, in side elevation by Fig. 5 and in end elevation by Fig. 11. This shaft 118 is secured to the end of the main frame of the machine by means of journal boxes 119 and 120. Keyed to one end of this shaft 118 is the hub 121 of a lever arm 122, to which is pivoted the end of the elongated reciprocating rod 117. In consequence of this connection, it is evident that as the main shaft rotates, the end shaft 118 will be oscillated through the instru-

mentality of the long rod 117 and the lever 122. This oscillation is in turn utilized to pull a punch stripping plate against the stock-bar to clamp the same accurately in position while the stock-bar is being punched, and then to move or permit this stripping plate to move out of clamping position while the punch is being withdrawn from the stock-bar, and thus enable the punch to be pulled away from the stock-bar to permit a subsequent feeding. This instrumentality comprises a U-shaped lever having its hub 123 keyed to a suitable portion of the shaft 118 and having its two parallel arms 124 and 125 supporting a pivot pin 126 at their upper ends. This pivot pin 126 carries a yoke-block 127 having two oppositely located lugs 128 and 129 which provide apertures through which freely pass the ends of parallel rods 130 and 131. These rods terminate at their extremities in handles 132 and 133, which are fastened securely in place by means of suitable pins and by means of which the rods 130 and 131 may be rotated for purposes of adjustment.

Intervening between the abutment shoulder of handle 132 and the apertured lug 128 are two tubes 134 and 135, which tubes are separated from one another by one or more distance rings 136. That is to say, in case it is desired to shorten the distance between the handle 132 and the hub 128, one or more of the rings indicated by 136 can be removed, or narrower rings substituted. A similar construction is resorted to with reference to the lower rod 131, and being clearly shown by Fig. 11 need not be specifically described. The rods 130 and 131 enter the machine body at one end thereof and pass longitudinally at right angles to the direction of feed of the stock-bar and terminate in a suitably located punch stripper plate 137 (see Figs. 9, 10 and 40). The ends of the rods which engage the plate 137 are screw-threaded, as indicated by the dotted lines in Fig. 9, thereby enabling the position of the block 137 to be very precisely determined and regulated by means of the hand levers 132 and 133. These rods 130 and 131 reciprocate transversely in direction to the feed of the incoming stock-bar, as indicated by the arrow N.

It may be observed that the block 137 is positioned at the side of the stock-bar adjacent the punch, the other side of the stock-bar being adjacent the die aperture into which the punch projects the plug of metal from the stock-bar. The block 137 is preferably provided with a replaceable block 138 having an aperture 139 therein, through which the punch for producing the aperture in the nut-blank may travel.

When the stock-bar is interposed in place preparatory to having the small rod 130

ture corresponding to the aperture in the nut-blank roughly punched out of the same, the block 137 will, through the above-described apparatus, be drawn tightly against 5 the stock-bar so as to assist the centering fingers in securely positioning the same. Then the small round punch will pass through the opening 139 and perforate the stock-bar, forcing the resultant plug 10 through the opening 162 in the punch die.

The punches and dies for perforating and shearing rough blanks from the stock-bar.—The purpose of this mechanism is to first 15 pierce a hole in the stock-bar adjacent its end, and then to cut off a portion of such stock-bar in such manner that said hole will be centrally located in such portion and serves as the nucleus, so to speak, for the threaded center-bore of the finished nut. 20 It is proposed to also successively trim the sides of the blank so as to prepare the same for the finishing operations, which take place at the other end of the machine, as will be presently described in detail. This 25 mechanism comprises a stationary wedge-shaped block 142 adapted to support the several trimming dies and the cutting off die, and which is rigidly mounted in the main frame of the machine adjacent one end. 30 This may be simply and efficiently accomplished by providing the block 142 with inclined side faces 143 and 144, and providing the main frame with a recess adapted to receive such die block, and having an under- 35 cut edge portion conforming to the inclination of the face 143 of the die supporting block. The gib 145 provides a right angle face 146 which has a sliding fit with a corresponding portion of the main frame of the 40 machine, and it also has an inclined face 147 conforming to the face 144 of the die supporting block. This gib 145 is provided with a pair of spaced internally threaded 45 apertures through which are screw threaded the ends of two long bolts, one of which is indicated by 148 on Fig. 40. The end of such bolt carries a nut 149 which bears against the end face of the main frame of the machine, and by screwing up these bolts, 50 the gib block 145 will be drawn home as tightly as may be desired, and as a consequence the die-supporting block 142 will be firmly and positively positioned in the frame. 55

55 The support for the underside of the die-supporting block preferably is so formed as to eliminate wear, and to that end, the under surface of the block 142 is provided with screw-threaded holes 150 and 151 which are 60 in registry with corresponding apertures in a hardened steel rest-plate 152 so as to enable the latter to be securely positioned in place by means of the screws 153. This hardened plate is useful in resisting wear. This hardened plate 152 rests on a counterpart rest-

plate 154 which is positioned on the upper surface of the rest-block 155 by means of the pins 156. This rest-block 155 simply consists of an integral piece having a shank 157 which has a driving fit in a corresponding aperture in the main frame of the machine and terminates in a square head, as above described. The die-supporting block is preferably formed of a single piece of machine steel having two upper and lower 70 apertures 158 and 159 through which may freely pass the rods 130 and 131 for actuating the above described bar-clamp 137. This block also comprises means for retaining the several dies for shearing and trimming the blanks and for discharging the material severed by the same. This construction is shown more clearly by Figs. 14 to 16. The rough shearing die consists of a piece of hardened steel, indicated by 80 160, secured adjacent a relatively small side extension or core-die 161 having a central die aperture 162 for coacting with the punch in punching out the core or central portion of the nut-blank. The die 160 also 85 provides the central die aperture 163 which coacts with a counterpart punch for the purpose of severing sections roughly approximating the shape of the finished nut-blank from the end of the stock-bar. To 90 enable this die-plate 160 to be adequately mounted on the die-block, this invention proposes a strong, massive extension or lug 164 extending forwardly at one side of the front face of the die-block 142. This extension 100 164 serves to coöperate in positioning the hardened flange backing plate 165. That is to say, this backing plate 165 has a base portion 166 apertured at 167 and 168 to enable machine screws to secure such base portion directly to the front face of the die-block by coöperating with the threaded holes 169 and 170, in the face of such die-block. The backing plate 165 also comprises the narrow elongated extension 171 which, 105 at its back, rests snugly against the massive lug 164 and has its exposed face adapted to cooperate with the edge of the die-plate proper to retain the same in place and form a shelf, so to speak, for supporting the same. 110 A somewhat similar construction is employed on the opposite side of the main die-block 142. This is to say, the latter provides a lug or extension 172, the intermediate portion of which is cut away or recessed, 115 as shown, to provide for the reception of the core-die backing-plate 173. This plate 173 provides a base portion 174 having end apertures 175 and 176 in registry with corresponding apertures such as 177, in the 120 main die-block so as to enable the said two parts to be secured together by means of machine screws. The intermediate portion of the backing plate 173, however, assumes 125 the form of an extension 179, which closely 130

fits into the above-mentioned cut-away portion of the lug 172, as shown on the drawings. The extension 179 of the core-die backing plate 173 also provides a perforation or channel 180 for conveying away the plugs which are forced out of the stock-bar by means of the core punch. As a matter of convenience, this perforation 180 is inclined horizontally toward the side of the machine on which the above-mentioned feed mechanism is arranged, and such inclined aperture is in registry with the corresponding perforation 181, which passes through the main die-supporting block 142. In this way, the plugs or chips are ultimately discharged from the main die-block 142 adjacent the point indicated by 182.

From the above, it will be perceived that the rough shearing die-plate proper may be set to rest at one end on the backing plate 165 and at the other end on the backing plate base 174. This will bring the edges of the die-plate adjacent the three screw-threaded holes 183, 184 and 185, which pass horizontally through the lug 172 of the main die-block. A corresponding series of set screws 186, 187 and 188 pass through these apertures and engage the edges of the die-plate and thereby positively position the same.

The die-supporting block also has a large central recess or aperture which is lined by means of a hardened steel bushing 190 having the form of a cylindrical shell provided with peripheral apertures for the discharge of chips as shown more clearly by Fig. 15. The object of using this hardened steel bushing is to provide some means intervening between the relatively soft machine steel of the die-supporting block and the series of trimming dies mounted in the central recess, so as to protect the machine steel against the wear of the hardened tool steel forming the trimming-dies. This bushing 190 is securely positioned and held firmly in place within the central recess of the die-supporting block by means of the three set-screws shown in Fig. 16, which set-screws also position the three trimming-dies. The first trimming-die 191 is located adjacent the rough shearing die 160, and has its trimming aperture in registry with the aperture 163 of the rough shearing die, so that when the blanks are forced through the aperture 163 they will properly enter the aperture in the first trimming-die. The set-screw 192 bears against the periphery of the first trimming-die 191 and holds the same against turning. The second trimming-die 193 is located adjacent the first trimming-die 191 and is held in place by means of set-screws in a similar manner, but is slightly spaced from the first die by means of the distance-block or ring 194. In like manner the last trimming-die 195 is positioned by means of a set-screw and spaced from the preceding die by means of

the annular distance-piece 196. As a result of this construction, the train of nut-blanks, which is forced through the several dies by the action of the shearing-punch, undergoes successive trimming operations by the action of the several dies, and in consequence the hexagonal peripheries of the various blanks are brought into a nearly finished condition. It will be understood that, as these blanks pass through the several trimming-dies, a slight amount of waste is removed from the same, and this escapes through a corresponding series of apertures in the bushing 190, which are in registry with similar apertures in the under wall of the die-supporting block 142. The train of nut-blanks then passes through an appropriate channel or aperture in the frame so as to be received by the curved end of the nut-blank conveyor 238.

The stop for the end of the stock-bar.—The purpose of this mechanism is to determine the position of the forward extremity of the stock-bar when the same is feeding into the machine. This mechanism is extremely simple and merely comprises a toe 201, shown more clearly by Fig. 9, which terminates in the path of the forward end of the stock-bar slightly at one side of the aperture in the shearing-die plate 160. This toe 201 depends from its attachment at 202 with the overlying hand-bar 203 pivoted at 204 and extending forwardly in the form of the hand-lever 205. By this means the operator is able to raise and lower this device, and thus to easily clear out the space around the die aperture when introducing a new stock-bar or otherwise manipulating the machine. This may be advisable since there will be a fair sized piece of scrap at the end of the stock-bar which may interfere with the regular feeding if not removed. The punch which severs the centrally apertured section from the end of the stock-bar is approximately hexagonal in cross section, and inasmuch as pieces of metal may occasionally adhere to the side of the same, this invention also proposes a stripper blade coacting with the side of the punch, as will now be described.

The support and stripper blade for the rough-blanking punch.—The function of this member is to support the punch, and at the same time remove from the same such portions of metal as may adhere thereto, and it consists of a stationary piece indicated by 206 on Figs. 9 and 10. This piece provides a base portion 207 having spaced apertures through which pass the retaining bolts 208 and 209 adapted to secure the same to the block 142. Laterally extending from this base portion is a wing 210 terminating in a hardened V-shaped end edge 211, which is so contoured as to closely conform to the side of the rough blanking punch. A screw 130

212 has its shank threaded into a suitable aperture in an adjacent portion 213 of the main frame so as to enable its head 214 to be brought into abutment with the side of the piece 206 and thereby enable close adjustment as to the position of the same to be readily and accurately secured.

The conveyer for the rough nut-blanks.—It will be understood from the foregoing that the operation of the above-described parts results in a succession of what may be termed rough nut-blanks; that is to say, blanks of metal having an unfinished central perforation and approximately 15 forming in contour to a hexagon, or other shape which it is desired to impart to the finished nut. This invention contemplates a machine in which these roughly finished blanks which are delivered at one end of the 20 machine will be properly conveyed to the other end of the machine, and at the latter point be properly taken care of and subjected to further operations. In the more abstract consideration of this invention, 25 these operations may be classified into two parts, *i. e.*, the rough blanking work and the finishing and crowning work. It is proposed to utilize a single member for carrying out both of these operations, and this is 30 done by utilizing one end of this member or mechanism in piercing and cutting from the end of the stock-bar a rough blank during its forward movement, and then at its other end crowning, trimming or otherwise 35 finishing a blank during the reverse reciprocation of such mechanism. In this way, it is proposed to utilize the full movement 40 of the mechanism which carries or impels the punches; using the forward movement for one series of operations and the return movement for another series of operations, and thus economizing in time, space and mechanism, and in general enhancing the 45 efficiency of the device. The mechanism for carrying out this operation embodies a novel device for receiving the nut-blanks and conveying the same from one end of the double-end punching mechanism to the other end thereof. In the form shown by the drawings, this conveying means assumes the form 50 of a reversely curved, twisted trackway in the form of an open, elongated framework or structure. This is shown clearly by Figs. 3 and 5 taken in connection with Fig. 40.

55 Turning first to Fig. 5, the blanks are received from the rough blank punch through the opening or aperture 220, and all take a symmetrical position between the three tracks 221, 222 and 223. These three tracks 60 are arranged equidistant from one another, as well as from the center of the aperture 220, so that the inner or effective guiding faces of these strips form the three alternate sides of a hexagon, so to speak. These 65 three equijacent strips are retained prop-

erly in position by means of a plurality of rings 224, each having equispaced recesses in their inner peripheries adapted to receive the strips, each strip being retained in its corresponding recess by means of a machine screw, indicated by 225 in dotted lines in Fig. 5. The end of this track may be secured in any suitable way to the end of the main frame of the machine in appropriate position to receive the nut-blanks, and preferably a split annular clamp 226 is used for this purpose. This clamp consists of two semi-annular sections hinged together by means of a machine screw 227, which also serves to secure each of these sections to the main frame of the machine. A screw 228 arranged on an appropriate lug 229 passes through an aperture therein and engages with the adjacent and additional lug 230 on the other member. By tightening up this screw, the two members are drawn firmly together and hold one end of the track in place, a machine screw 231 being also preferably used to more securely determine the position of the split clamp 226. That is to say, the screw 231 is threaded to the frame of the machine and when it is screwed up, its head clamps the piece 230 against the frame and prevents such piece from turning to get the tracks out of the preadjusted alignment.

Turning to Fig. 40, it will be noticed that the trackway above described extends from the forward or rough swaging end of the main frame in the form of a compound curve; that is to say, its general appearance has the form of an open loop, somewhat like a hook, and it terminates in a direction the reverse of that of the nut-blanks being discharged by the shearing punch. By a closer inspection, it will also be noticed that the track is twisted about its own axis so as to impart a spiral effect to the three component bar elements of such track, and thus interchange the position of the nuts of such bars. This method of construction possesses points of superiority both from the standpoint of mechanical engineering and from the standpoint of smoothness of operation of the stream of nuts passing along such trackway. It is found that the tendency to crowd is entirely obviated, or reduced to a minimum, and that the nut-blanks may be fed regularly and without difficulty. This open framework terminates adjacent a standard 232, which is mounted on the upper surface of the main frame and retained in place by means of the machine bolts 233, as appears more clearly from Figs. 3, 4 and 5. At its upper end, such standard assumes the form of an annular hub-like portion 234, to which is bolted the ring 235 by means of screws 236, thereby securing the track ring 224 in place. The opposite side of this hub-like portion 234 extends in the form of a

trough-like portion 237, which supports the end of the horizontal nut guide or trough 238. This track guide is clearly shown in end elevation by Figs. 3 and 5, and consists of an elongated channel bar which extends longitudinally above the main frame of the machine and terminates adjacent the rear end thereof. This is shown more clearly by Fig. 40. It is to be noted that the extremity of this bar 238 has its bottom portion cut away as indicated by the aperture 239.

The means for successively receiving and carrying the nut-blanks through the further steps of the operation will now be described.

15. *The mechanism for transferring the nut-blanks from the conveyer to the roulette.*—It may be perceived at this point that, owing to the somewhat rough and irregular contour of the nut-blanks which are pushed 20 along the conveyer in the form of a long train of blanks, the foremost nut-blank may be more or less displaced in its position. That is to say, at one time the foremost unit of the train of nut-blanks may be well 25 advanced with respect to the extremity of the conveyer, and at another time it may be positioned more to the rear of such extremity. On the other hand, in an automatic machine of this character one highly important attribute to smoothness and positiveness of action will reside in an accurate 30 and unfailing placing of the nut-blanks. In order, therefore, to provide a mechanism having the capacity of compensating for the 35 variable positions of the nut-blanks at the delivery end of the conveyer, this invention proposes to intervene what may be termed a picker mechanism between the conveyer and the roulette which carries the nuts 40 through the various finishing operations, such as crowning, repunching, retrimming and the like. According to this invention a device such as that shown by Fig. 18 and comprising a pair of tong-like spring arms 45 is mounted adjacent the extremity of the conveyer and adapted to horizontally reciprocate so as to advance into engagement with the nut-blank carried at the end of said conveyer and withdraw the same therefrom, and thus positively position the same 50 in a predetermined vertical plane. This mechanism is shown more plainly by Figs. 17 to 21 inclusive.

55 Turning first to Figs. 18 and 19, a pair of spring fingers or tongs 240 and 241 are secured, by means of screws such as 242 to a block 243 so as to lie parallel with one another, but spaced apart approximately somewhat less than the maximum diagonal of a 60 nut-blank. This block 243 is mounted to slide in a horizontal direction in a suitable stationary part of the frame of the machine, as shown by the drawings, and is actuated through an extension 244, which terminates 65 in the slotted end 245. An actuating lever

246 is pivoted at its one end to the pivot pin 247 and at its other end carries the pin 248, which moves in the slot in the end 245. This lever is actuated by means of the roller 249 which rides in contact with the periphery 70 of the cam 250 which is fixed to a shaft 251 mounted in journal boxes 252 arranged at one side of the machine. Roller 249 may be held in contact with cam 250 by any suitable means, such as the usual spring 500. This 75 shaft is in turn driven by the beveled gear 253 in mesh with the gear 72' which is secured to the shaft 72, which at one end carries the gear 254 in mesh with the gear 255 mounted on the main shaft 6. As a result 80 of this mechanism, the spring fingers or tongs 240 and 241 are caused to advance toward the end of the nut-blank conveyer 238 and, by reason of the slot 239 they are able 85 to pass over and frictionally grip the nut-blank at the head of the train of blanks. Consequently, during the withdrawal of the 90 spring fingers or tongs 240 and 241, this nut-blank will be removed and carried to a position such that it may be engaged by a second pair of tongs which are arranged to slide vertically and transversely to the movement of said first-mentioned tongs. The 95 second tongs are shown more clearly by Figs. 20 and 17 and indicated by reference numerals 256 and 257. These second tongs are secured to a block 258 fixed to a member 259, which is in turn adjustably fixed in position on a vertically reciprocating block 260 by means of the screw 261. This block slides 100 vertically in the ways 262, and has a pivot pin 263 projecting rearwardly through slot 264 in the vertical ways 262 (see Fig. 22). This pivot pin 263 carries a conventional form of sliding block which slidably connects with the end 265 of the vertically oscillating lever 266. This lever is pivoted at its distant end to the pivot 267 and is actuated by means 105 of an intermediately located roller 268 in engagement with the cam 269 (see Figs. 17 and 21), also fast to the shaft 251. 110

It will, from the foregoing, be understood that when the first tong mechanism withdraws the nut-blank from the end of the conveyer, such blank is to be transferred to the vertically moving pair of tongs. This is accomplished by means of an upper plunger 270, which reciprocates between the tongs 240 and 241, and which is normally held in a retracted position by means of the 115 spring 271 (see Fig. 17). At the proper instant, this plunger is advanced and pushes the nut-blank from between the tongs 240 and 241, and then between the tongs 256 and 257, it being, of course, understood that the latter tongs are now in their elevated position through the operation of the lever 266. The means for operating the plunger 270 consists in a lever 22 (shown more clearly 120 by Figs. 17 and 22), which is pivoted at an 125 130

intermediate point to the pivot pin 273 carried by a suitable standard rising from the frame of the machine. The actuating end of this lever carries an adjustable screw 274 which, during the forward advance of the lever impacts against the end of the plunger 270 and in turn advances the same. The lever 272 is actuated by means of a roller 275 which contacts with the cam 276 fixed to the shaft 251. A spring 277 (shown in Fig. 17) operates to keep the roller 275 properly pressed against the cam surface 276. The spring 277 is stronger than the spring 271.

In order to transfer the blanks from the vertically moving tongs, this invention proposes a lower plunger 278. This is shown more clearly by Figs. 20, 21 and 22. This plunger 278 reciprocates horizontally and is pivotally connected with an uprising bent lever 279, which is pivoted at 280, and at its upper end carries the roller 281 which rides around the cam 282 and is intermittently actuated thereby. Roller 281 may be held in contact with the cam 282 by any suitable means, such as the usual spring 501. Consequently, each time the plunger 278 operates, a nut-blank will be forced from the vertically moving tongs and will be received by the adjacent spoke of the roulette or spoke-like structure, as will be presently described. Through this mechanism the blanks are very certainly and accurately positioned and transported through the several finishing operations.

The roulette for carrying the nut-blanks through the successive finishing operations.—The detailed construction of the preferred form of roulette is shown more particularly by Figs. 23 and 24. A shaft 283 passes from the rear or discharge end of the machine through the main frame, and terminates adjacent the end of the double-headed reciprocating punch-carrying frame. At its forward end, this shaft tapers and carries the hub 284 of the roulette. This hub is securely retained in position by means of a pressure plate 285, which is positioned by the nut 286 on the end of the shaft 283. The hub of this roulette provides a series of equispaced radiating spoke-like members 287, 287, 287, and, inasmuch as these are similar in character, but one need be described. This radiating portion extends to the rear, *i. e.*, in an axial direction, a little less than one-half the total length of the hub 284 and provides a grooved channel or trackway in which an intervening block 288 may slide in a radial direction, but is restrained against any other movement relative to the part 284.

A tong-block 289 has a transverse movement on the intervening block 288, as shown more clearly by Fig. 24, so as to permit of slight lateral adjustments of such block if desired. The block extends forwardly in

the form of a shank 290 which carries the nut 291 at its foremost extremity. This nut enables the parts to be secured rigidly in place by clamping the same up. For the purpose of securing exact radial adjustments of the block 289, a nut 292, which engages the radial bolt 293, is provided, as will be understood. Each arm or spoke of this roulette is formed by a pair of spring fingers 294 and 295, which, adjacent their extremities, provide V-shaped nicks 296 adapted to engage the corners of the hexagonal nut-blank and hold the same with sufficient firmness by reason of the spring tension of the arms or fingers 294 and 295. These fingers 294 are in turn secured to the tong-blocks 289 by means of appropriate nuts and bolts, indicated by 297. This roulette is arranged and disposed as shown more clearly by Fig. 40, so that as the shaft 283 is intermittently rotated through an angle of 60 degrees, the spring fingers of the roulette will successively pass by a position directly opposite the plunger 278 which forces the blank from the above-described vertically moving carrier to the finger of the roulette which is at the instant in registry therewith. In this way every time the plunger 278 operates, a nut-blank will be positioned in the roulette. The blank is first carried through a dummy step constituting a sixth of a revolution of the roulette in the direction indicated by the arrow on Fig. 23. Thereafter it is again carried through another sixth of a revolution, so as to bring it into position opposite the flattening punch 298 which is mounted on one end of the double-ender reciprocating punching head. The nut-blank is supported from the other side by the anvil 299 which is adjustably mounted in the stationary part of the main frame as by means of the adjusting screw 300. This is shown best by Fig. 24. After this operation, the roulette is again turned through 60 degrees, bringing the blank opposite the crowning-die 301, shown in front end elevation by Fig. 23, in longitudinal section by Fig. 25, and in rear elevation by Figs. 26 and 27. This crowning-die has the form of an elongated cylinder which is secured to the main frame 115 by means of the engaging screw threads 302, and is adjusted therein by turning the nut forming its rear, exposed end. The working end of this die is countersunk, as indicated by 303, so that, during the advance 120 of the plunger 304 carried by the reciprocating head, the nut-blank will be forced into this recess 303 and thus be given a "crown". It may be stated in this connection that since the forces employed during 125 this operation are considerable, there is a tendency for the nut-blank to more or less firmly adhere to the die 301, and to that end means are provided for forcing the same out of such die to enable the crowned 130

blank to be carried along by the spring arms of the roulette and positioned opposite the repunching die. This ejector consists of a plunger 305 which reciprocates in the central bore of the crown-die 301. This plunger 305 preferably has enlarged bearing portions 306 and 307, as shown by Fig. 25, and protrudes from the rear of the frame in the form of a screw-threaded shank 308 which is tapped to the gudgeon bolt 309 and locked thereon by means of the nut 310. This gudgeon bolt provides usually right and left bearing pins or gudgeons 311. These pins are seated in the bifurcated ends 312 of the safety lever 313. This lever is of compound character, and comprises an upper member 314 which is pivoted to the lower member 313 by means of the pivot pin 315, but is normally prevented from angular movement relative thereto by means of the safety shear pin 316. This shear pin 316 is constructed of steel sufficiently soft to give way under excessive strains so as to prevent fracture of other parts of the mechanism. This lever is in turn secured to the end of the shaft 317, which is mounted in bearings 318 secured to the rear end of the stationary frame, and at its other end this shaft carries the lever 319 which, by means of the rod 320, is connected to one extremity of the cam actuated lever 321 which is pivoted at 322, and at its upper extremity carries the roller 323 which is actuated by the cam 324. Accordingly, plunger 305 will be advanced at appropriate intervals and thus will force out the crowned nut-blank, and the latter will be then carried by the roulette to the repunching-die 325, shown on Fig. 23. This repunching-die provides an aperture 326 for receiving the scrap. After the repunching operation, the blank is then carried by the roulette to the retrimming-die 327, shown on Figs. 23 and 24. This retrimming-die has a hexagonal aperture of appropriate size, and when the plunger 328 carried by the main reciprocating head advances, it will force the nut-blank through this hexagonal aperture in the retrimming-die 327, thus shaving off any excess metal on the edges of the blank. Through the successive movements of the plunger 328, the train of blanks is then forced through the die 327, and these blanks in turn ultimately are discharged through the aperture 329, shown by Figs. 22 and 27.

The automatic rotator for the roulette.—In the forgoing it has been stated that the roulette turns intermittently through angles of 60 degrees for the purpose of successively presenting the nut-blanks carried by the fingers thereof through the several finishing operations. It now becomes necessary to disclose the means instrumental in automatically producing this motion of the roulette. Preliminary to a

description of this, it may be pointed out that it is essential that the travel of the roulette shall be very accurately determined so that the blanks may be brought to the exact positions, and in like manner it is 70 equally essential that when these successive positions have been attained, the roulette shall be locked against any slight displacement due to backlash or other causes. This mechanism contains provision for accomplishing these objects and the same may be best understood by referring to Figs. 27, 28 and 29.

The shaft 283 to which the roulette is secured, projects rearwardly from the main frame of the machine and carries three notched wheels, the one being in the nature of a ratchet wheel adapted to coact with a ratchet mechanism in turning the roulette, the second in the nature of a step wheel adapted to coact with a removable stop in limiting the movement in one direction, and the third being in the nature of a stop wheel adapted to coact with another stop (which is also a safety device) in limiting the movement in the opposite direction, and thus coact with the second wheel in bringing the roulette to a fixed stationary and accurately determined position.

The ratchet wheel 342 is keyed fast to the shaft 283 a slight distance from the end of the same, and this remaining distance is occupied by the hub 343 of the oscillating ratchet carrier 344. This hub is retained in place by means of an end-plate 346 which is held on the shaft by means of the nut 347. The upper extremity of the ratchet carrier 344 is provided with the ratchet 345 which extends downwardly into engagement with the ratchet wheel 342. This ratchet carrier is oscillated through the instrumentality of the reciprocating arm 348, which, at its lower end, is pivotally connected between the two arms 349 of the ratchet carrier. This arm 348 derives its movement from a roller 350 which rides in contact with the cam 351. Its other extremity 352 may be prevented from side play in any suitable manner, as by connecting the same by sliding block with the shaft 251, as will be readily understood. In consequence with this arrangement a rotation of the shaft 251 will cause the arm 348 to reciprocate and thus intermittently rotate the roulette shaft.

To prevent an overfeed or excessive partial rotation of the roulette shaft, a stop lever 353 is pivoted at the end of the main frame and terminates in a hardened end adapted to be swung into engagement with the serrated periphery of the wheel 354, thereby arresting the rotation of the latter at a definite and exactly determined point. This lever 353 is inserted and withdrawn through the link 355 moved by the actuating lever 356. This lever is pivoted at an 130

intermediate point 357 to the main frame of the machine and its upper end carries the roller 358 which rides in contact with the periphery of the cam 359, so that during each revolution of the shaft 251 the stop lever 353 will be withdrawn to enable the roulette to be turned and will then be thrown back in place to cause an arrest of its forward rotation at the precisely determined point. Roller 358 may be held in contact with the cam 359 by any suitable means, such as the usual springs 502.

In order to prevent any reflex action of the roulette, this invention also proposes the third notched wheel 360 which is adapted to be engaged by the suitably pointed end of the plunger 361 which is suitably supported in the bearing 362 adjustably mounted on the main frame of the machine. The rear end of this stop plunger 361 provides the two gudgeons 363 which are engaged by bifurcated end 364 of the actuating lever 365. This lever is pivoted at an intermediate point and at its upper end carries a roller 366 which is actuated by the cam 367. Roller 366 may be held in contact with the cam 367 by any suitable means, such as the usual spring 503. Accordingly, as this cam rotates, the lever 365 will be intermittently operated thus producing a reciprocating action in the stop plunger 361 and thereby releasing or locking the roulette wheel in position as may be appropriate at the instant.

The double-ender reciprocating punch head.—This part of the apparatus is in the nature of a sub frame and is shown more clearly by Figs. 30 and 31. The reciprocating head itself is composed of a large solid casting 368 which is suitably fashioned at one end for adjustably supporting the block 369 which carries the preliminary acting punches, *i. e.*, the punches for roughly aperturing the stock-bar, and the punch for shearing an apertured section of the stock-bar and forcing the same through the first trimming-dies. This block is held in place in any suitable manner, as by means of the clamp 370. At the other end of this reciprocating head 368 are arranged the several finishing punches. Thus the flattened punch 298 is, by means of a suitable bushing such as that indicated by 372, held to slightly project from the end of the head 368 and is adjusted in position by means of the wedge 373. In like manner the punch for forcing the blanks through the final trimming-dies is shown by 328 and is adjusted by the wedge 375, all in the same manner. The head 368 is actuated from the main drive shaft 6 by means of the sliding block 378 which is journaled to the shaft 6 and is adapted to slide up and down through suitable bearings in 368, thus reciprocating the latter and with the necessary degree of power. The block 378 is pivoted in eccen-

tric relation to the shaft 6, as shown by Fig. 31, as by means of the eccentric 422. One salient characteristic of this feature of this invention resides in the fact that both the advance and the return strokes of the punch-supporting head 368 are utilized fully and effectively and thus there is substantially no lost motion or lost time in the operation of the machine. During the advance stroke, the blanks are roughly formed and during the return stroke the roughly formed blanks, which have, in the meantime, been transplanted to the other end of the machine, undergo the finishing operation and are finally ejected through the chute 379, shown in Fig. 40. Of course, the reciprocating head 368 is provided with ample sliding bearings in the main frame, as will be readily understood.

The means for receiving and discharging the waste from the machine.—During the several operations on the stock, material is removed in the form of waste and this falls into the two chutes 380 and 381. In these chutes are arranged corresponding spiral drives 382 and 383 which are driven through the gears 384 and 385 which are in mesh with the gear 386 mounted on the transverse shaft 387. These chutes or pans 380 and 381 are preferably spring pressed upwardly against the rotating drivers 382 and 383 by means of springs 388, as will be readily understood, thereby maintaining the contact necessary for discharging all of the chips. The shaft 387 carries a sprocket wheel 389 at its other end and this is driven by means of the sprocket chain 390 which derives its motion from the sprocket 391 on the shaft 72. A pair of idlers 392 serve to keep the sprocket wheel out of contact with the cam 110 on the main shaft 6.

The clearer for the retrimming-die.—This device is shown best by Fig. 20, and has for its purpose keeping the face of the retrimming-die 327 free and clear from particles of scrap metal which may tend to adhere to the same during the process of retrimming the blank. This consists of a lever 330 terminating at its end in a knife 331 adapted to pass over the face of the trimming-die 327 and scrape off any adhering particles of scrap. This lever 330 is reciprocated at appropriate intervals by means of the rod 332 which connects one arm of the lever 330 with the lever 333 mounted on the shaft 334, which, at its other end, carries the lever 335. This latter lever is in turn pivotally connected with one arm of the cam-actuated lever 336 which is pivotally supported on the bracket 337 by means of the pin 338. The other arm of this lever terminates in the form of a toe 339 (see Fig. 20) which rides around the periphery of the cam 340 and may be held thereagainst by a spring 504. This cam provides the depression 341 130

so that when the toe drops down the same, the various links and levers above described will operate in such manner as to cause the knife 331 to make a quick sweep across the face of the retrimming-die 327 and thus clear the same.

During the course of the foregoing description, the construction and mode of operation of the double acting head which carries the punches at each end may have been rendered more or less obvious, but completeness of disclosure requires a more detailed discussion of the same.

The hand-operated and the automatic means for stopping the machine.—It will be apparent that from time to time the operator will wish to momentarily stop the working of this machine for various purposes, and therefore the same embodies hand levers adapted to be actuated for this purpose. At other times, certain irregularities in the operation of the machine which might not come under the immediate observation of the operator might render it necessary that the same should automatically stop until the defect has been cured, and therefore this invention proposes a certain safety automatic stop which will operate so as to prevent any damage. Turning to Figs. 12, 36, 37, 38 and 39, 394 indicates the operating pawl and clutch of conventional design which is interposed between the main driving gear 5 and the main driving shaft 6, which clutch is capable of being disengaged through the operation of the pawl 394 so as to disconnect said shaft 6 from the source of power. The pawl 394 is normally free and rotates with the clutch member without interference, and is so constructed that if an element is interposed in the path of its free end so as to swing the same from the dotted position shown to its position shown in full lines, then the disengagement of the clutch will immediately follow. This invention proposes as one means of operating this pawl 394, a dog 395 (see Fig. 12), which is pivoted at 396 and which is actuated through the link 397. This link is in turn connected with the end of the long hand lever 398, pivoted at 399 and terminating in an operating handle 400 located adjacent the feeding mechanism for the stock-bar. The dog 395 is normally out of the path of the pawl 394 of the clutch, but if the operator should for any reason desire to stop the machine, it is only necessary to grasp the handle 400 and throw the same forward, as shown by the arrow in Fig. 40, whereupon the dog 395 will be swung down into the path of the pawl 394 and will thus throw the same in such manner as to disconnect the clutch and cause the stoppage of the machine.

The machine also provides a hand lever near its discharge end which operates in connection with an automatic stop and

which works through the dog 401 which is supported by the pivot 402 carried by the bracket 403 secured to the side of the machine (see Fig. 12). A link in the form of a long rod 404 (see Fig. 1) extends through the machine on the opposite side thereof, is connected with the rock shaft 405 which runs longitudinally, and terminates at the discharge end of the machine where it carries the catch 406 (see Fig. 27). The hand lever 408 is pivoted at 409 and terminates in the handle 410 which may be grasped and operated to release the catch 406 and enable the link 404 to move longitudinally under the influence of a properly connected spring 505 to throw the dog 401 into the path of the pawl 394 to stop the machine in the manner above described. This lever 408, however, is also connected with a means for automatically operating the same, and this will now be described.

In the above description, it has been pointed out that a plunger 361 is adapted to be seated in an appropriate recess in the wheel 360 which rotates with the roulette. It may happen that through some obstruction or the like, the roulette wheel may not come into the precise position required for the perfect operation of the machine, and in that event, the plunger 361 will be unable to advance forwardly into its normal position because of the fact that the recess or notch in the wheel 360 will not be in proper registry therewith. This will mean that the lever 365 will not be able to ride in continuous contact with the cam 367; in other words, the roller 366 will assume an abnormal position out of contact with the depressed periphery of the cam 367. Now the lever 365, as will be seen by turning to Figs. 32 and 33, has a short arm 411 which is integrally connected with its hub and extends a short distance therefrom. A trip lever 412 is pivoted at 413 to the extremity of the lever 411 and at its uppermost extremity terminates in a rounded end 414 which normally is in the position shown by Fig. 32, but which when the roller 366 lies an abnormal distance from the cam surface 367 will be swung close to the periphery of the cam 415. When in this abnormal position, it lies in the path of the projection 416 so that as the shaft 251 rotates, this projection 416 will engage the rounded end 414 and swing the upper end of the trip lever 412 in a right hand direction. The other end of this lever 412 bears against the corresponding end of the bell crank lever 417 and this will swing the same to move the arm 418 in the direction indicated by the arrow of Fig. 32. This motion is transmitted to the link 419 and through the bell crank lever 420 and the link 421 is imparted to the hand lever 408, thereby having the effect of lifting the handle 410 and releasing the catch 406 and thus stopping the operation.

of the machine, as has been previously described.

It will thus be perceived that this invention is one well adapted to achieve the several ends and modes of operation enumerated in the foregoing, and that it is capable of automatically and with a minimum amount of attention producing finished nut-blanks from commercial stock-bars. While the machine is naturally of a rather complex character and is composed of many parts, still, considering the results accomplished and the compactness of the same, it embodies a high degree of simplicity.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. A mechanism of the nature disclosed, comprising, in combination, a reciprocatory member, metal-working implements carried thereby and adapted to operate, respectively, on each stroke of the member, a feeder for introducing stock in the path of the implement acting on one stroke, and means for receiving and conveying the stock operated on into the path of the implement acting on the other stroke, whereby said reciprocatory member may be working effectively at each stroke thereof.

2. A machine of the nature disclosed comprising in combination, a reciprocating member, a punch carried thereby, a feeder for interposing a stock-bar in the path of said punch to enable the latter to sever sections therefrom, and a curved trackway for successively receiving said sections and conveying the same in a curved path reversing in direction toward the other end of the machine.

3. A machine of the nature disclosed comprising in combination, a reciprocating member, a metal working implement carried at opposite ends thereof, a feeder for interposing stock in the path of the implement on the one end of said reciprocating member, means for successively receiving and conveying to the other end of said machine the stock operated on by said first-mentioned implement, and a device for successively interposing such stock into the path of the implement on the other end of said machine whereby said reciprocating member may be working effectively at each stroke thereof.

4. A machine of the nature disclosed comprising in combination, a reciprocating

punch, means for feeding stock into operative relation therewith to enable operations to be performed thereon, and a trackway in the form of an open loop adapted to receive said stock and transport the same to a distant part of the machine.

5. A machine of the nature disclosed comprising in combination, a reciprocating punch, means for feeding stock into operative relation with said punch, an open frame trackway consisting of a plurality of track members arranged equidistant from one another and equidistant from a common center, adapted to receive the stock, said trackway extending in the form of an open loop toward a distant portion of the machine.

6. A machine of the nature disclosed comprising, in combination, a main frame, a sub-frame supported by said main frame and adapted to reciprocate therein, a punch carried at the end of one of said parts, another punch carried at the other end of said part, means for conveying stock into operative relation with said first-mentioned punch to enable said stock to be pre-formed thereby during an advance reciprocation of one of said parts, and means for conveying the pre-formed stock to the other end of the machine in operative relation with the second-mentioned punch to enable the latter to further operate on said stock during a return reciprocation of said part.

7. A machine of the nature disclosed comprising, in combination, a main frame, a sub-frame reciprocally carried thereby, a metal working implement carried at each end of said sub-frame, and means for continuously interposing stock into operative relation with each of said implements, whereby both the advance and return reciprocations of said sub-frame may be effectively utilized.

8. A machine of the nature disclosed comprising, in combination, a main frame, a sub-frame reciprocally carried thereby, a metal working implement arranged adjacent each end of said sub-frame, and means for first interposing stock in the path of one of said implements at one end of said sub-frame and then carrying said stock, after being preliminarily formed, to the other end of said sub-frame, whereby both forward and return reciprocations of said sub-frame may be effectively utilized.

9. A machine of the nature disclosed comprising, in combination, a main frame, a sub-frame reciprocally carried thereby, a metal working implement arranged adjacent each end of said sub-frame, means for feeding stock into operative relation with the implement at one end of said sub-frame to enable the latter to pre-form said stock, and means comprising a reversely curved track adapted to receive said pre-

formed stock and convey the same into the path of the implement at the other end of said sub-frame, whereby the implement at such end may further operate on said stock.

- 5 10. A machine of the nature disclosed comprising, in combination, a main frame, a sub-frame reciprocally carried thereby, a punch mounted on one end of said sub-frame, a die mounted on and adjacent part 10 of the main frame in registry with said punch, means for interposing stock between said punch and die to enable said punch to operate thereon, a trackway for receiving the stock subsequent to such operation and 15 adapted to convey the same to the other end of the sub-frame, an implement mounted adjacent the other end of said sub-frame, and means for receiving the stock from said trackway and positioning the same in suitable registry with said implement, whereby 20 the latter may operate during a return reciprocation of said sub-frame.

11. A machine of the nature disclosed comprising, in combination, a main frame, 25 a sub-frame reciprocally carried thereby, a punch mounted on one end of said sub-frame, a die mounted on an adjacent part of said main frame in registry with said punch, means for introducing the end of a stock-bar between said punch and die to enable portions to be sheared into said die, a trackway adapted to receive blanks from the open end of said die curving reversely 30 in direction toward the other end of said sub-frame for conveying the blanks to said end, a punch mounted on the other end of said sub-frame, a die mounted on an adjacent part of the main frame, and means for receiving blanks from said trackway and 35 interposing the same between the punch and die to enable the former to further operate on said blanks.

12. A machine of the nature disclosed comprising, in combination, a main frame, 45 a sub-frame reciprocally carried thereby, a punch mounted on the end of said sub-frame, a die mounted on an adjacent part of the main frame in registry with said punch, means for feeding a stock-bar into 50 the path of said punch to enable the same to shear blanks therefrom during a forward reciprocation of said sub-frame, a channel leading toward the end of the main frame adapted to convey the blanks, an open frame trackway consisting of a plurality of track members arranged equidistant from one another and from a common axis, said trackway having one end secured to the main frame to receive the nut-blanks 55 and reversely curving with its other end directed toward the opposite end of the machine, a straight line trackway connected with the other end of said open frame trackway and leading to a point adjacent the other end of said sub-frame, a metal

working implement mounted adjacent the last-mentioned end of said sub-frame, and means for receiving stock from said straight line trackway and interposing the same in the path of said implement.

- 70 13. A machine of the nature disclosed comprising, in combination, a main frame, a sub-frame reciprocally mounted thereon, a punch carried by the sub-frame, a feeder for translating a stock-bar into the path of 75 said punch, means for transversely adjusting the position of said stock-bar to accurately center the same in registry with the punch, and a curved trackway for successively receiving the several blanks delivered 80 by said punch and conveying the same in a path reversely curving in a direction toward the other end of the machine.

14. A machine of the nature disclosed comprising, in combination, a main frame, 85 a sub-frame reciprocally carried thereby, a metal working implement carried by the opposite ends of said sub-frame, a feeder for translating stock into the path of the implement on one end of said sub-frame, a 90 bar-centering device for automatically transversely shifting said stock-bar into registry with said implement, means for successively receiving and conveying to the other end of said machine the stock operated on by said first-mentioned implement, and a device for successively interposing such stock into the path of the implement on the other end of said sub-frame, whereby the latter may be working effectively at 95 each stroke thereof.

15. A machine of the nature disclosed comprising, in combination, a main frame, a sub-frame reciprocally mounted thereon, a punch mounted on said sub-frame so as to 105 reciprocate therewith, means for longitudinally translating a stock-bar to interpose its end in the path of the punch, an automatic bar-centering mechanism adapted to engage the opposite longitudinal edges of said 110 stock-bar to bring its end into accurate registry with said punch, and a trackway in the form of an open loop adapted to receive the blanks sheared from the end of said stock-bar by said punch and transport the 115 same to a distant part of the machine.

16. A machine of the nature disclosed comprising, in combination, a main frame, a sub-frame reciprocally carried thereby, a punch mounted on said sub-frame so as to 120 be reciprocated therewith, means for longitudinally translating the end of a stock-bar into operative relation with said punch, a bar-centering mechanism adapted to laterally shift the end of said stock-bar to 125 bring the same into accurate registry with said punch, an open frame trackway consisting of a plurality of equidistant track members adapted to receive the blanks severed from said stock-bar, said trackway 130

extending in the form of an open loop toward a distant portion of the machine.

17. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, mechanism for receiving and retaining the stock, and means for causing a progressive intermittent movement of said mechanism to successively position said stock in operative relation with the second mentioned punch to enable the latter to further operate on said stock during a return reciprocation of said part.

18. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a rotary mechanism for receiving and positioning the stock, and a device for rotating said mechanism to shift the position of the stock carried thereby whereby such stock may be subjected to different operations.

19. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette adapted to receive and position the stock whereby it may be operated upon by the punch carried at the other end of one of said parts, and a rotator for successively turning said roulette step by step whereby the stock may be differently positioned to undergo different operations.

20. A machine of the nature disclosed comprising in combination, a main frame, a subframe supported by said main frame and adapted to reciprocate thereon, a punch carried at the end of one of said parts, another punch carried at the other end of one of said

parts, means for conveying stock into operative relation with said first mentioned punch to enable said stock to be pre-formed thereby during an advance reciprocation of one of said parts, means for conveying the pre-formed stock to the other end of the machine, a roulette comprising a plurality of radial arms adapted to receive said stock, and a rotator for turning said roulette step by step to differently position the stock carried thereby whereby the same may be subjected to different operations.

21. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette comprising a plurality of radial arms adapted to receive said stock, a rotatable shaft carrying said roulette, and a device co-operating with said shaft to turn the same step by step to move said roulette through successive positions.

22. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette having a plurality of radial spring arms adapted to receive said stock, and a rotator for turning said roulette step by step to successively position said arms.

23. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette having a plurality of radial spring arms adapted to receive the stock, and means for rotating said roulette step by step to cause said arms to successively assume positions opposite predetermined points to enable said stock to undergo different operations.

24. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, means adapted to advance into engagement with the stock to remove the same from said conveyer and adapted to bring such stock exactly into a predetermined position relative to said second mentioned punch.
25. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device adapted to advance into engagement with the stock to withdraw the same from said conveyer, and a mechanism movable transversely to said device adapted to receive and accurately position the stock carried thereby.
26. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device having a pair of spring tongs adapted to be reciprocated toward the end of said conveyer to enable said tongs to frictionally engage the stock therein, and means for cooperating with said device whereby the stock may be successively removed from said conveyer and accurately positioned relative to said second mentioned punch.
27. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to reciprocate in alinement with said conveyer to receive stock therefrom, a plunger, a spring normally maintaining said plunger out of the path of the stock, intermittent means operative against the resistance of said spring adapted to advance said plunger to discharge the stock, and a roulette adapted to receive the stock and accurately position the same relative to said second mentioned punch.
28. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to advance into engagement with the stock to remove the same from said conveyer, a plunger for forcing the stock from said device, a spring normally maintaining said plunger in its retracted position, means operative against the resistance of said spring adapted to reciprocate said plunger to force the stock from said device, and a mechanism adapted to receive the stock and accurately position the same relative to said second mentioned punch.
29. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to reciprocate in alinement with said conveyer to receive stock therefrom, a plunger, a spring normally maintaining said plunger out of the path of the stock, intermittent means operative against the resistance of said spring adapted to advance said plunger to discharge the stock, and a roulette adapted to receive the stock and accurately position the same relative to said second mentioned punch.

30. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers slidably mounted in alinement with said conveyer, a plunger, a spring normally maintaining said plunger retracted relative to said fingers, mechanism co-acting with said plunger to actuate the same against the resistance of said spring, cam means adapted to intermittently operate said mechanism to cause a reciprocation of said plunger, and means for receiving and accurately positioning the stock discharged by said plunger.
31. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device having a pair of spring tongs adapted to be reciprocated toward the end of said conveyer to enable said tongs to frictionally engage the stock, means for operating said device whereby the stock may be successively withdrawn from the end of said conveyer, a mechanism movable transversely to said device adapted to receive the stock carried thereby, and means co-operating with said mechanism for accurately positioning the stock relative to said second mentioned punch.
32. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer adapted to reciprocate toward the same, a plunger, a spring maintaining said plunger in a normal position, means operative against the resistance of said spring
- adapted to reciprocate said plunger to enable the latter to discharge stock from said device, a mechanism movable transversely to said device to receive the stock discharged therefrom, a second mechanism co-operating with said first mentioned mechanism for receiving the stock from the former and positioning the same, and means for actuating said second mechanism.
33. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to advance into engagement with stock carried thereby to remove the same, a plunger, a spring normally retaining said plunger in its retracted position, means operative against the resistance of said spring adapted to reciprocate said plunger, mechanism movable transversely to said device adapted to receive the stock discharged by said plunger, and means co-operating with said mechanism for accurately positioning the blanks relative to said second mentioned punch.
34. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the ends of said conveyer adapted to reciprocate in alinement with said conveyer, a plunger, a spring normally maintaining said plunger retracted relative to said fingers, intermittent means operative against the resistance of said spring adapted to advance said plunger, mechanism movable transversely to said device adapted to receive stock discharged by said plunger, and a second mechanism co-operating with said first mentioned mechanism for accurately positioning the stock relative to said second mentioned punch.
35. A machine of the nature disclosed comprising in combination, a main frame, a subframe supported by said main frame

and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device having a pair of spring tongs adapted to be reciprocated toward the end of said conveyer to enable said tongs to frictionally engage stock, means for operating said device whereby the stock may be successively withdrawn from the end of said conveyer, a mechanism comprising a pair of spring tongs arranged transversely to said first mentioned tongs and adapted to receive the stock carried thereby, means for reciprocating said mechanism transversely to the movement of said device, and a roulette for receiving the stock from said mechanism and for bringing the same into a succession of predetermined positions.

36. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a pair of jaws for gripping stock, automatic means for bringing said jaws into gripping contact with the stock-bar, independent hand-controlled means for releasing said stock-bar from said jaws, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

37. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an ad-

vance reciprocation of one of said parts, said means comprising a pair of gripping jaws, automatic means for resiliently urging said jaws into gripping contact with the stock-bar, independent hand-operated means for releasing the pressure on one of said jaws to enable said stock-bar to be manually moved, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

38. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a reciprocating member, a jaw carried thereby, a second member hinged to said reciprocating member, a jaw carried by said second member, a cam slidably mounted in said reciprocating member and adapted to co-act with said second member to swing the same and cause the said two jaws to approach into gripping position, a lever having an elongated sliding bearing with said cam and adapted to reciprocate the same, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

39. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said

parts, said means comprising a reciprocating member, a jaw carried thereby, a second member hinged to said reciprocating member, a jaw carried by said second member, a spring-pressed part carried by said second member, a cam slidably mounted on said reciprocating member and adapted to actuate said second member through said part to cause said jaws to move into gripping position; automatic means for sliding said cam, means for conveying the blanks sheared from said stock-bar to the other end of the machine, mechanism for receiving a plurality of said blanks, and means for causing 10 a progressive intermittent movement of said mechanism to successively position said blanks in operative relation with the second mentioned punch to enable the latter to further operate on said blanks during a return 15 reciprocation of said part.

40. A machine of the nature disclosed comprising in combination, a main frame, a subframe supported by said main frame and adapted to reciprocate thereon, a punch 25 carried at the end of one of said parts adapted to shear a stock-bar into a plurality of blanks, another punch carried at the other end of said part adapted to operate on blanks, means for conveying an elongated 30 stock-bar into operative relation with said first mentioned punch to enable the latter to produce a blank therefrom during an advance reciprocation of one of said parts, said means comprising a horizontally reciprocating member, a second member pivoted about an axis extending parallel to the direction of movement of said first mentioned member, an actuating member for swinging said second member and having a sliding 35 elongated connection therewith, means for operating said actuating member to swing said second member toward said first member, means for conveying the blanks sheared from said stock-bar to the other end of the 40 machine, mechanism for receiving a plurality of said blanks, and means for causing a progressive intermittent movement of said mechanism to successively position said blanks in operative relation with the second 45 mentioned punch to enable the latter to further operate on said blanks during a return 50 reciprocation of said part.

41. A machine of the nature disclosed comprising in combination, a main frame, 55 a subframe supported by said main frame and adapted to reciprocate thereon, a punch carried at the end of one of said parts adapted to shear a stock-bar into a plurality of blanks, another punch carried 60 at the other end of said part adapted to operate on blanks, means for conveying an elongated stock-bar into operative relation with said first mentioned punch to enable the latter to produce a blank there- 65 from during an advance reciprocation of

one of said parts, said means comprising an elongated frame member, a jaw supporting member arranged to slidably reciprocate horizontally on said frame member, a jaw carrying arm hinged to said member about 70 an axis in parallelism with the movement of said member, a lever terminating at one end in a horizontally elongated bearing piece adapted to swing up and down with said lever, a bearing block in engagement 75 with said bearing piece and connected with said arm whereby the same may be oscillated with the rise and fall of said bearing piece, means for reciprocating said member and oscillating said lever at appropriate 80 periods, means for conveying the blanks sheared from said stock-bar to the other end of the machine, mechanism for receiving a plurality of said blanks, and means for causing 85 a progressive intermittent movement of said mechanism to successively position said blanks in operative relation with the second mentioned punch to enable the latter to further operate on said blanks during a return reciprocation of said part.

42. A machine of the nature disclosed comprising in combination, a main frame, a subframe supported by said main frame and adapted to reciprocate thereon, a punch carried at the end of one of said parts 90 adapted to shear a stock-bar into a plurality of blanks, another punch carried at the other end of said part adapted to operate on blanks, means for conveying an elongated stock-bar into operative relation 95 with said first mentioned punch to enable the latter to produce a blank therefrom during an advance reciprocation of one of said parts, said means comprising a drive shaft, a face cam arranged on one end thereof, a circumferential cam arranged adjacent said face cam, a lever horizontally oscillated by said circumferential cam, a jaw carrying member horizontally reciprocated by said lever, a second lever vertically oscillated by said face cam, means actuated by said second lever to enable the stock-bar to be clamped and advanced during a forward reciprocation of said member, means for conveying the blanks sheared from said 100 stock-bar to the other end of the machine; mechanism for receiving a plurality of said blanks, and means for causing a progressive 105 intermittent movement of said mechanism to successively position said blanks in operative relation with the second mentioned punch to enable the latter to further operate on said blanks during a return reciprocation of said part.

43. A machine of the nature disclosed 110 comprising in combination, a main frame, a subframe supported by said main frame and adapted to reciprocate thereon, a punch carried at the end of one of said parts adapt- 115 ed to shear a stock-bar into a plurality of 120

blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a member adapted to reciprocate in a horizontal direction, a jaw 10 carried thereby, a second member pivoted to said reciprocating member about an axis parallel with the direction of movement of said reciprocating member, a jaw carried by said second member, a spring pressued 15 part carried by said second member, a cam mounted to vertically move in said reciprocating member and adapted to actuate said second member through said part to cause said jaws to move into gripping position, a vertically oscillating arm terminating in a horizontally elongated bearing piece having a sliding bearing with said cam, means for reciprocating said first mentioned reciprocating member and 20 vertically oscillating said arm, means for conveying the blanks sheared from said stock-bar to the other end of the machine, mechanism for receiving a plurality of said blanks, and means for causing a progressive 25 intermittent movement of said mechanism to successively position said blanks in operative relation with the second mentioned punch to enable the latter to further operate on said blanks during a return recip- 30 ration of said part.

44. A machine of the nature disclosed comprising in combination, a main frame, a subframe supported by said main frame and adapted to reciprocate thereon, a punch 40 carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a vise mechanism 45 adapted to be reciprocated in a horizontal direction, a power shaft having a circumferential cam, a lever connected at one end to said vise mechanism and at the other end co-operating with said circumferential cam, an intermediate pivot bolt, adjustable 50 mountings for said pivot bolt, a block having a pivotal relation with said pivot bolt, means for adjustably securing said lever to said block, means for conveying the blanks sheared from said stock-bar to the other end 55 of the machine, mechanism for receiving a plurality of said blanks, and means for causing a progressive intermittent movement of said mechanism to successively position said blanks in operative relation with 60

the second mentioned punch to enable the latter to further operate on said blanks during a return reciprocation of said part.

45. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a drive shaft, a circumferential cam thereon, a lever co-operating at one end with said cam, a pivot adjustably secured to said lever at an intermediate point, adjustable bearings for said pivot, an extension piece adjustably secured to the free end of said lever, and vise mechanism adapted to be reciprocated, an adjustable bearing connecting said vise mechanism with said extension whereby the former may be actuated by the latter, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

46. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a reciprocating vise mechanism, a drive shaft having a cam, a lever oscillated by said cam, a rocking block slidably engaging with an intermediate portion of said lever, means for locking the two together, an adjustably positionable pivot block journaled in said rocking block, adjustable means connecting said vise mechanism with said lever, means for conveying the blanks sheared from said stock-bar to the other end of the machine, mechanism for receiving a plurality of said blanks, and means for causing a progressive intermittent movement of said mechanism to successively position said blanks in oper- 120

- ative relation with the second mentioned punch to enable the latter to further operate on said blanks during a return reciprocation of said part.
47. A machine of the nature disclosed comprising in combination, a main frame, a sub-frame supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a reciprocating vise mechanism, a drive shaft carrying a cam, a lever arm having one end connected with said cam and adjustably pivoted at an intermediate point, an extension piece overlapping and bolted to one end of said lever, a clamping piece bolted to said extension piece and overlapping an end lip of said lever, means adjustably pivoting said extension piece to said reciprocating vise mechanism, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.
48. A machine of the nature disclosed comprising in combination, a main frame, a sub-frame supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising two members adapted to abut opposite sides of the stock-bar to position the same, pivoted arms supporting said members, means for simultaneously causing each of said members to approach the other at an established predetermined rate of movement, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to fur-
- ther operate on said blanks during a return reciprocation of said part.
49. A machine of the nature disclosed comprising in combination, a main frame, a sub-frame supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising two members adapted to be brought into abutment with the sides of the stock-bar to center the same, arms supporting said members and restricting the direction of movement thereof, cam means coacting with said arms adapted to positively move each of said arms at an established predetermined rate, whereby a corresponding movement will be imparted to said members, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.
50. A machine of the nature disclosed comprising in combination, a main frame, a sub-frame supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a pair of arms each pivotally secured to a common base, a bar centering finger carried by each of said arms, an actuating finger carried by each of said arms, a cam coöperating with said actuating fingers adapted to oscillate said arms to move said centering fingers toward one another, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.
51. A machine of the nature disclosed com-

prising in combination, a main frame, a sub-frame supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a pair of arms, each pivoted at an intermediate point to a common base, a centering finger carried by each arm on the same side of its pivot, said centering fingers terminating opposite to one another, an actuating finger carried by each of said arms on the other side of said pivot and terminating opposite one another, a cam intervening between said fingers and movable to simultaneously actuate the same, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

52. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a pair of arms, each pivoted at an intermediate point to a common base, a centering finger carried by each arm on the same side of its pivot, said centering fingers terminating opposite to one another, an actuating finger carried by each of said arms on the other side of said pivot and terminating opposite one another, a cam adapted to reciprocate between said actuating fingers to simultaneously actuate the same, means for conveying the blanks sheared from said stock-bar to the other end of the machine, mechanism for receiving a plurality of blanks, and means for causing a progressive intermittent movement of said mechanism to successively position said blanks in operative relation with the second mentioned punch to enable the latter to further operate on said blanks during a return reciprocation of said part.

53. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a pair of arms, each pivoted at an intermediate point to a common base, a centering finger carried by each arm on the same side of its pivot, said centering fingers terminating opposite to one another, an actuating finger carried by each of said arms on the other side of said pivot and terminating opposite one another, a two-part wedge-shaped cam adapted to reciprocally translate between said actuating fingers to simultaneously actuate the same, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

54. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a feedway for the stock-bar, a pair of arms each pivoted above and below said feedway, respectively, said arms having parts extending over said feedway, a centering finger carried by each of said arms and terminating above and below said feedway in registry therewith, said arms having portions extending to one side of said feedway, means arranged at one side of said feedway co-operating with said portions to actuate said centering fingers, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

punch to enable the latter to further operate on said blanks during a return reciprocation of said part.

55. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a feedway for the stock-bar, a pair of bar centering fingers arranged above and below said feedway in registry therewith, cam means arranged at one side of said feedway adapted to simultaneously actuate said centering fingers, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

56. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a feedway, a pair of arms pivoted to a common base above and below said feedway, respectively, a centering finger carried by each of said arms and terminating opposite one another above and below said feedway, said arms each having extensions on the other side of said pivot points, said extensions terminating at one side of said feedway, actuating fingers carried by each of said extensions and terminating opposite one another, a cam intervening between the extremities of said actuating fingers and adapted to be reciprocated to simultaneously actuate the same, means for conveying the blanks sheared from said stock-bar to the other end of the machine, mechanism for receiving a plurality of said blanks, and means for causing a progressive intermittent movement of said mechanism to successively position said

blanks in operative relation with the second mentioned punch to enable the latter to further operate on said blanks during a return reciprocation of said part.

57. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a shaft extending from one side of the main frame to the other, a cam arranged on one extremity of said shaft, a stock-bar feeder arranged a distance from said shaft and adapted to feed the stock-bar in a direction substantially parallel with said shaft, levers interposing between said cam and said stock-bar feeder to actuate the same through the instrumentality of said shaft, a feedway for receiving the stock-bar, a shaft arranged on the opposite side of said machine at right angles to said main shaft and in mesh therewith, a cam arranged on said second shaft, means extending from said cam to the other side of said machine adjacent said stock-bar feeder, a bar-centering mechanism connected with and actuated by said means and extending toward the center of the machine in the direction of the feedway for the stock-bar, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said part.

58. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a main driving shaft extending from one side of the machine to the other side thereof, a stock-bar feeder arranged at one side of the machine a distance from said shaft, means extending from said

shaft to said feeder, a cam mechanism adapted to actuate the same for feeding a stock-bar in a direction in substantial parallelism with said shaft, a bar-centering mechanism adapted to operate on said stock-bar at a point adjacent the center of the machine, means intervening between said centering mechanism and the main shaft on the opposite side of said machine for actuating said centering mechanism, means for conveying the blanks sheared from said stock-bar to the other end of the machine, mechanism for receiving a plurality of said blanks, and means for causing a progressive intermittent movement of said mechanism to successively position said blanks in operative relation with the second mentioned punch to enable the latter to further operate on said blanks during a return reciprocation of said parts.

59. A machine of the nature disclosed comprising in combination, a main frame, a subframe supported by said main frame and adapted to reciprocate thereon, a punch carried at the end of one of said parts adapted to shear a stock-bar into a plurality of blanks, another punch carried at the other end of said part adapted to operate on blanks, means for conveying an elongated stock-bar into operative relation with said first mentioned punch to enable the latter to produce a blank therefrom during an advance reciprocation of one of said parts, said means comprising a stationary feedway for the stock-bar, means for automatically 90

35 and intermittently feeding said stock-bar along said feedway, a bar-centering mechanism adapted to engage said stock-bar at a point adjacent its forward end to positively position said stock-bar, means for conveying 95

40 the blanks sheared from said stock-bar to the other end of the machine, mechanism for receiving a plurality of said blanks, and means for causing a progressive intermittent movement of said mechanism to successively position said blanks in operative 100

45 relation with the second mentioned punch to enable the latter to further operate on said blanks during a return reciprocation of said part.

60. A machine of the nature disclosed comprising in combination, a reciprocating member, a metal working implement carried at opposite ends thereof, a feeder for interposing stock in the path of the implement on the one end of said reciprocating member, means for successively receiving and conveying to the other end of said machine the stock operated on by said first-mentioned implement, a device for successively interposing such stock into the path of the implement on the said other end of said machine whereby said reciprocating member may be working effectively at each stroke thereof, and a stop mechanism for 105

65 controlling the operation of the machine op-

erative under an abnormal operation of said device.

61. A machine of the nature disclosed comprising, in combination, a main frame, a sub-frame supported by said main frame and adapted to reciprocate therein, a punch carried at the end of one of said parts, another punch carried at the other end of said part, means for conveying stock into operative relation with said first mentioned punch to enable said stock to be pre-formed thereby during an advance reciprocation of one of said parts, means for conveying the pre-formed stock to the other end of the machine in operative relation with the second-mentioned punch to enable the latter to further operate on said stock during a return reciprocation of said part, and a stop mechanism for controlling the operation of the machine operative under an abnormal operation of said last mentioned means.

62. A machine of the nature disclosed comprising, in combination, a main frame, a sub-frame reciprocally carried thereby, a metal working implement carried at each end of said sub-frame, means for continuously interposing stock into operative relation with each of said implements, whereby both the advance and return reciprocations of said sub-frame may be effectively utilized, 95 a stop mechanism, and connections between said stop mechanism and said means to render the former effective during an abnormal operation of the latter.

63. A machine of the nature disclosed comprising, in combination, a main frame, a sub-frame reciprocally carried thereby, a metal working implement arranged adjacent each end of said sub-frame, means for first interposing stock into the path of one of said implements at one end of said sub-frame and then carrying said stock, after being preliminarily formed, to the other end of said sub-frame, whereby both forward and return reciprocations of said sub-frame may be effectively utilized, and a normally ineffective stop mechanism connected with the means for interposing stock at the said other end of said sub-frame.

64. A machine of the nature disclosed comprising, in combination, a main frame, a sub-frame reciprocally carried thereby, a punch mounted on one end of said sub-frame, a die mounted on an adjacent part of the main frame in registry with said punch, means for interposing stock between said punch and die to enable said punch to operate thereon, a trackway for receiving the stock subsequent to such operation and adapted to convey the same to the other end of the sub-frame, an implement mounted adjacent the other end of said sub-frame, means for receiving the stock from said trackway and positioning the same in suitable registry with said implement, whereby 130

the latter may operate during a return reciprocation of said sub-frame, and a normally ineffective stop mechanism connected with said last mentioned means and adapted to become operative when the latter imperfectly positions the stock.

65. A machine of the nature disclosed comprising, in combination, a main frame, a sub-frame reciprocally carried thereby, a punch mounted on one end of said sub-frame, a die mounted on an adjacent part of said main frame in registry with said punch, means for introducing the end of a stock bar between said punch and die to enable portions to be sheared into said die, a trackway adapted to receive blanks from the open end of said die curving reversely in direction toward the other end of said sub-frame for conveying the blanks to said other end, a punch mounted on the other end of said sub-frame, a die mounted on an adjacent part of the main frame, means for receiving blanks from said trackway and interposing the same between the punch and die to enable the former to further operate on said blanks, and a normally ineffective stop mechanism connected with said means and adapted to be rendered operative when such means imperfectly interposes a blank.

66. A machine of the nature disclosed comprising, in combination, a main frame, a sub-frame reciprocally carried thereby, a punch mounted on the end of said sub-frame, a die mounted on an adjacent part of the main frame in registry with said punch, means for feeding a stock-bar into the path of said punch to enable the same to shear blanks therefrom during a forward reciprocation of said sub-frame, a channel leading toward the end of the main frame adapted to convey the blanks, an open frame trackway consisting of a plurality of track members arranged equidistant from one another and from a common axis, said trackway having one end secured to the main frame to receive the nut-blanks and reversely curving with its other end directed toward the opposite end of the machine, a straight line trackway connected with the other end of said open frame trackway and leading to a point adjacent the other end of said sub-frame, a metal working implement mounted adjacent the last-mentioned end of said sub-frame, means for receiving stock from said straight line trackway and interposing the same in the path of said implement, and a normally ineffective stop mechanism connected with said last means and adapted to be rendered operative when such means imperfectly interposes the stock.

67. A machine of the nature disclosed comprising, in combination, a main frame, a sub-frame reciprocally carried thereby, a metal working implement carried by the opposite ends of said sub-frame, a feeder for

translating stock into the path of the implement on one end of said sub-frame, a bar-centering device for automatically transversely shifting said stock-bar into registry with said implement, means for successively receiving and conveying to the other end of said machine the stock operated on by said first-mentioned implement, a device for successively interposing such stock into the path of the implement on the other end of said sub-frame, whereby the latter may be working effectively at each stroke thereof, and a normally ineffective stop mechanism adapted to be operated by an abnormal operation of said device.

68. A machine of the nature disclosed comprising, in combination, a conveyer for a train of blanks, a device adapted to advance into engagement with a blank to withdraw the same from said conveyer, a mechanism movable transversely to said device adapted to receive the blank carried thereby, automatic stop mechanism adapted to discontinue the operation of the machine under inaccurate positioning of a blank by said transversely movable mechanism, and means for further operating on said blank.

69. A machine of the nature disclosed comprising, in combination, a conveyer for a train of blanks, a device having a pair of spring-tongs adapted to be reciprocated toward the end of said conveyer to enable said tongs to frictionally engage the blank at the head of the train of blanks, means for operating said device whereby the blanks may be successively removed from the end of said conveyer, automatic mechanism adapted to stop the operation of said operating means.

70. A machine of the nature disclosed comprising, in combination, a conveyer for a train of blanks, a device having a pair of spring-tongs adapted to be reciprocated toward the end of said conveyer to enable said tongs to frictionally engage a blank at the head of the train of blanks, means for operating said device whereby the blanks may be successively withdrawn from the end of said conveyer, a mechanism movable transversely to said device adapted to receive the blanks carried thereby, and a stop mechanism co-operating with said mechanism, and adapted to stop the operation of the latter mechanism under abnormal operation thereof.

71. A machine of the nature disclosed comprising, in combination, a conveyer for a train of blanks, a device comprising a pair of spring-fingers mounted opposite the end of said conveyer and adapted to reciprocate toward the same, a plunger, a spring maintaining said plunger in a normal position, means operative against the resistance of said spring adapted to reciprocate said plunger to enable the latter to successively discharge blanks from said device, a mech-

anism movable transversely to said device adapted to receive the blank discharged therefrom, and a stop mechanism coöperating with said mechanism, and adapted to 5 stop the operation of the latter mechanism under abnormal operation thereof.

72. A machine of the nature disclosed comprising, in combination, a conveyer for a train of blanks, a device comprising a pair 10 of spring-fingers mounted opposite the end of said conveyer and adapted to advance into engagement with a blank at the head of said train to engage and remove the same from said conveyer, a plunger, a spring normally retaining said plunger in its retracted 15 position, means operative against the resistance of said spring adapted to reciprocate said plunger, a mechanism movable transversely to said device adapted to receive the blank discharged by said plunger, and a stop mechanism coöperating with said mechanism, and adapted to stop the operation of the latter mechanism under abnormal operation thereof.

73. A machine of the nature disclosed comprising, in combination, a conveyer for a train of blanks, a device comprising a pair of spring-fingers mounted opposite the end of said conveyer, and adapted to reciprocate 20 in alinement with said conveyer, a plunger, a spring normally maintaining said plunger, retracted relative to said fingers, intermittent means operative against the resistance of said spring adapted to advance said 25 plunger, a mechanism movable transversely to said device adapted to receive the blank discharged by said plunger, and a stop mechanism coöperating with said mechanism, and adapted to stop the operation of the latter mechanism under abnormal operation thereof.

74. A machine of the nature disclosed comprising, in combination, a conveyer for a train of blanks, a device comprising a pair 45 of spring-fingers slidably mounted in alinement with said conveyer, a plunger, a spring normally maintaining said plunger retracted relative to said fingers, mechanism coacting with said plunger to actuate the same 50 against the resistance of said spring, cam means adapted to move intermittently to cause a reciprocation of said device, a mechanism movable transversely to said device adapted to receive the blank discharged by 55 said plunger, and a stop mechanism coöperating with said mechanism, and adapted to stop the operation of the latter mechanism under abnormal operation thereof.

75. A machine of the nature disclosed comprising, in combination, a conveyer for a train of blanks, a device having a pair of spring-tongs adapted to be reciprocated toward the end of said conveyer to enable 60 said tongs to frictionally engage a blank at the head of the train of blanks, means for

operating said device whereby the blanks may be successively withdrawn from the end of said conveyer, and mechanism comprising a pair of spring-tongs arranged transversely to said first-mentioned tongs 70 and adapted to receive the blank carried thereby, means for reciprocating said mechanism transversely to the movement of said device, and a stop mechanism coöperating with said mechanism, and adapted to stop 75 the operation of the latter mechanism under abnormal operation thereof.

76. A machine of the nature disclosed comprising, in combination, mechanism for receiving and retaining a plurality of blanks, 80 means for causing a progressive intermittent movement of said mechanism to successively position said blanks, mechanism for simultaneously operating on a plurality of said blanks, and an automatic stop mechanism adapted to discontinue the operation of the machine under inaccurate positioning of a blank by said receiving and retaining mechanism, and means for supplying said first-mentioned mechanism with blanks. 90

77. A machine of the nature disclosed, comprising in combination, a rotary mechanism for receiving and positioning a plurality of blanks, means for simultaneously operating upon a plurality of said blanks when 95 positioned by said mechanism, an automatic stop mechanism adapted to discontinue the operation of the machine under inaccurate positioning of a blank by said rotary mechanism, and a device for rotating said mechanism to shift the position of the blanks carried thereby whereby such blanks may be subjected to different operations. 100

78. A machine of the nature disclosed comprising, in combination, a roulette 105 adapted to receive and position a plurality of blanks, means for supplying said roulette with blanks, a mechanism comprising a plurality of implements adapted to simultaneously operate on blanks carried by said roulette, an automatic stop mechanism adapted to discontinue the operation of the machine under inaccurate positioning of a blank by said roulette, and a rotator for successively turning said roulette step by 110 step whereby the individual blanks may be differently positioned to undergo different operations by said mechanism. 115

79. A machine of the nature disclosed, comprising, in combination, a roulette having a plurality of radial spring-arms, a rotator for turning said roulette step by step to successively position said arms, means for supplying the arms with blanks as they assume positions opposite a predetermined 120 point, a mechanism comprising a plurality of implements adapted to simultaneously operate on the blanks carried by said arms, and an automatic stop mechanism adapted 125 to discontinue the operation of said mecha- 130

nism under inaccurate positioning of a blank by said roulette.

80. A machine of the nature disclosed comprising, in combination, a roulette having a plurality of radial spring-arms, means for rotating said roulette step by step to cause said arms to successively assume positions opposite predetermined points, a mechanism having a plurality of implements arranged at opposite points and adapted to simultaneously operate on the blanks positioned by said roulette, one of said implements being adapted to discharge blanks from said roulette, an automatic stop mechanism adapted to discontinue the operation of the machine under inaccurate positioning of a blank by said roulette, and means for automatically supplying the arms of said roulette with blanks when the same assume positions opposite a point of supply.

81. A machine of the nature disclosed, comprising, in combination, a conveyer for a train of blanks, a device adapted to advance into engagement with a blank and remove the same from said conveyer and adapted to bring said blank exactly into a predetermined position, a reciprocating head carrying an implement adapted to be brought into engagement with said blank to operate on the same, and an automatic stop mechanism operative to discontinue the reciprocations of said head during an abnormal operation of said machine.

82. A machine of the nature disclosed comprising, in combination, a conveyer for a train of blanks, a device adapted to advance into engagement with a blank to withdraw the same from said conveyer, a mechanism movable transversely to said device adapted to receive and position the blank carried thereby, a reciprocating head having a punch adapted to operate on said blank, and an automatic stop mechanism operative to discontinue the reciprocations of said head during an abnormal operation of said machine.

83. A machine of the nature disclosed comprising, in combination, a conveyer for a train of blanks, a device having a pair of spring-tongs adapted to be reciprocated toward the end of said conveyer to enable said tongs to frictionally engage the blank at the head of the train of blanks, means for operating with said device whereby the blanks may be successively removed from the end of said conveyer and brought to a predetermined position, a reciprocating head having an implement adapted to advance to operate on said blank, and an automatic stop mechanism operative to discontinue the reciprocations of said head during an abnormal operation of said machine.

84. A machine of the nature disclosed comprising, in combination, a conveyer for

a train of blanks, a device comprising a pair of spring-fingers mounted opposite the end of said conveyer and adapted to reciprocate toward the same, means operative to reciprocate said device to enable the latter to successively withdraw blanks from said conveyer, a mechanism adapted to receive the blanks from said means and bring the same into a predetermined position, a reciprocating head having implements adapted to operate on said blanks when so positioned, and an automatic stop mechanism operative to discontinue the reciprocations of said head during an abnormal operation of said machine.

85. A machine of the nature disclosed comprising, in combination, a conveyer for a train of blanks, a device comprising a pair of spring-fingers mounted opposite the end of said conveyer and adapted to advance into engagement with a blank at the head of said train to engage the same and remove it from said conveyer, a plunger for forcing the blank from said device, a spring normally maintaining said plunger in its retracted position, means operative against the resistance of said spring adapted to reciprocate said plunger to force the blank from said device, a mechanism adapted to receive the blank and carry the same into a predetermined position, a reciprocating head carrying an implement adapted to operate on said blank when so positioned, and an automatic stop mechanism operative to discontinue the reciprocations of said head during an abnormal operation of said machine.

86. A machine of the nature disclosed comprising, in combination, a conveyer for a train of blanks, a device comprising a pair of spring-fingers mounted opposite the end of said conveyer and adapted to reciprocate in alignment with said conveyer, a plunger, a spring normally maintaining said plunger out of the path of a blank, intermittent means operative against the resistance of said spring adapted to advance said plunger to discharge a blank, a roulette adapted to receive said blank, a reciprocating head having an implement adapted to operate on said blank in the roulette, and an automatic stop mechanism operative to discontinue the reciprocations of said head during an abnormal operation of said machine.

87. A machine of the nature disclosed comprising, in combination, a conveyer for a train of blanks, a device comprising a pair of spring-fingers slidably mounted in alignment with said conveyer, a plunger, a spring normally maintaining said plunger retracted relative to said fingers, mechanism coacting with said plunger to actuate the same against the resistance of said spring, cam means adapted to intermittently operate said mechanism to cause a reciprocation of

5 said plunger, means for receiving and positioning the blank discharged by said plunger, a reciprocating head carrying an implement adapted to operate on said positioned blank, and an automatic stop mechanism operative to discontinue the reciprocations of said head during an abnormal operation of said machine.

10 88. A machine of the nature disclosed, comprising, in combination, a conveyer for a train of blanks, a device having a pair of spring-tongs adapted to be reciprocated toward the end of said conveyer to enable said tongs to frictionally engage a blank at the 15 head of a train of blanks, means for operating said device whereby the blanks may be successively withdrawn from the end by said conveyer, a mechanism movable transversely to said device adapted to receive the 20 blanks carried thereby, means coöperating with said mechanism for positioning said blanks, a reciprocating head having an implement adapted to operate on the positioned blanks, and an automatic stop mechanism operative to discontinue the reciprocations of said head during an abnormal 25 operation of said machine.

30 89. A machine of the nature disclosed comprising, in combination, a conveyer for a train of blanks, a device comprising a pair of spring-fingers mounted opposite the end of said conveyer and adapted to reciprocate toward the same, a plunger, a spring maintaining said plunger in a normal position, means operative against the resistance of said spring adapted to reciprocate said plunger to enable the latter to successively discharge blanks from said device, a mechanism movable transversely to said device 35 adapted to receive the blank discharged therefrom, a second mechanism coöperating with said first-mentioned mechanism for receiving the blank from the former and positioning the same, a reciprocating head having an implement adapted to operate on said blanks in said second mechanism, and an automatic mechanism operative to discontinue the reciprocations of said head during an abnormal operation of said machine.

40 90. A machine of the nature disclosed comprising, in combination, a conveyer for a train of blanks, a device comprising a pair of spring-fingers mounted opposite the end of said conveyer and adapted to advance 45 into engagement with a blank at the head of said train to engage and remove the same from said conveyer, a plunger, a spring normally retaining said plunger in its retracted position, means operative against the resistance of said spring adapted to reciprocate said plunger, a mechanism movable transversely to said device adapted to receive the blank discharged by said plunger, means for accurately positioning the 50 blanks, a reciprocating head having an im-

70 plement adapted to operate on the blanks so positioned, and an automatic stop mechanism operative to discontinue the reciprocations of said head during an abnormal operation of said machine.

75 91. A machine of the nature disclosed comprising, in combination, a conveyer for a train of blanks, a device comprising a pair of spring-fingers mounted opposite the end of said conveyer adapted to reciprocate in alignment with said conveyer, a plunger, a spring normally maintaining said plunger retracted relative to said finger, intermittent means operative against the resistance of said spring adapted to advance said plunger, a mechanism movable transversely past said plunger, a second mechanism co-operating with said first-mentioned mechanism for accurately positioning the blanks, a reciprocating head having an implement 80 for operating on the blanks so positioned, and an automatic stop mechanism operative to discontinue the reciprocations of said head during an abnormal operation of said machine.

85 92. A machine of the nature disclosed comprising, in combination, a conveyer for a train of blanks, a device comprising a pair of spring-fingers slidably mounted in alignment with said conveyer, a plunger, a spring normally maintaining said plunger retracted relative to said fingers, mechanism co-acting with said plunger to actuate the same against the resistance of said spring, cam means adapted to move intermittently to cause a reciprocation of said device, a mechanism movable transversely to said device, adapted to receive the blank discharged by said plunger, a second mechanism for receiving the blank from said first-mentioned mechanism to carry the same through successive positions, a reciprocating head having a plurality of implements adapted to successively operate on said blank as the latter assumes its successive positions, and an automatic stop mechanism operative to discontinue the reciprocations of said head during an abnormal operation of said machine.

95 93. A machine of the nature disclosed comprising, in combination, a conveyer for a train of blanks, a device having a pair of spring-tongs adapted to be reciprocated toward the end of said conveyer to enable said tongs to frictionally engage a blank at the head of the train of blanks, means for operating said device whereby the blanks may be successively withdrawn from the end of said conveyer, a mechanism comprising a pair of spring-tongs arranged transversely to said first-mentioned tongs and adapted to receive the blank carried thereby, means for reciprocating said mechanism transversely to the movement of said device, a roulette for receiving the blanks from said mechanism and

for bringing the same into a succession of predetermined positions, a reciprocating head having a plurality of implements adapted to operate on said blanks in the roulette, and an automatic stop mechanism operative to discontinue the reciprocations of said head during an abnormal operation of said machine.

94. A machine of the nature disclosed, comprising, in combination, a conveyer for a train of blanks, a device comprising a pair of spring-arms mounted opposite the end of said conveyer and adapted to reciprocate toward the same, a plunger, a spring maintaining said plunger in a normal position, means operative against the resistance of said spring adapted to reciprocate said plunger to enable the latter to successively force blanks from said device, a mechanism comprising a pair of spring-tongs arranged and movable transversely to said device and adapted to receive the blank discharged therefrom, means for reciprocating said mechanism, a roulette adapted to receive the blanks from said mechanism, a reciprocating head having a plurality of implements adapted to simultaneously operate on the blanks carried by said roulette, and an automatic stop mechanism operative to discontinue the reciprocations of said head during an abnormal operation of said machine.

95. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, mechanism for receiving and retaining the stock, means for causing a progressive intermittent movement of said mechanism to successively position said stock in operative relation with the second mentioned punch to enable the latter to further operate on said stock during a return reciprocation of said part, and an automatic stop mechanism connected with said positioning means and adapted to operate when the stock is inaccurately positioned.

96. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette comprising a plurality

of radial arms adapted to receive said stock, a rotator for turning said roulette step by step to differently position the stock carried thereby whereby the same may be subjected to different operations, and a normally ineffective stop mechanism operative when the stock is inaccurately positioned.

97. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette adapted to receive and position the stock whereby it may be operated upon by the punch carried at the other end of one of said parts, a rotator for successively turning said roulette step by step whereby the stock may be differently positioned to undergo different operations, and a normally ineffective stop mechanism operative when the stock is inaccurately positioned.

98. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette comprising a plurality of radial arms adapted to receive said stock, a rotator for turning said roulette step by step to differently position the stock carried thereby whereby the same may be subjected to different operations, and a normally ineffective stop mechanism operative when the stock is inaccurately positioned.

99. A machine of the nature disclosed comprising in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a roulette comprising a plurality

of radial arms adapted to receive said stock, a rotatable shaft carrying said roulette, a device coöperating with said shaft to turn the same step by step to move said roulette through successive positions, and a normally ineffective stop mechanism operative when the stock is inaccurately positioned.

100. A machine of the nature disclosed comprising, in combination, a main frame, 10 a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other 15 end of the machine, a roulette having a plurality of radial spring arms adapted to receive said stock, a rotator for turning said roulette step by step to successively position said arms, and a normally ineffective stop 20 mechanism operative when the stock is inaccurately positioned.

101. A machine of the nature disclosed comprising, in combination, a main frame, a subframe supported by said main frame 30 and adapted to reciprocate thereon, a punch carried at the end of one of said parts, another punch carried at the other end of one of said parts, means for conveying stock into operative relation with said first mentioned 35 punch to enable said stock to be pre-formed thereby during an advance reciprocation of one of said parts, means for conveying the pre-formed stock to the other end of the machine, a roulette having a plurality of radial 40 spring arms adapted to receive the stock, means for rotating said roulette step by step to cause said arms to successively assume positions opposite predetermined points to enable said stock to undergo different operations, and a normally ineffective stop mechanism operative when the stock is inaccurately positioned.

102. A machine of the nature disclosed comprising, in combination, a main frame, 50 a subframe supported by said main frame and adapted to reciprocate thereon, a punch carried at the end of one of said parts, another punch carried at the other end of one of said parts, means for conveying stock into operative relation with said first mentioned 55 punch to enable said stock to be pre-formed thereby during an advance reciprocation of one of said parts, means for conveying the pre-formed stock to the other end of the 60 machine, means adapted to advance into engagement with the stock to remove the same from said conveyer and adapted to bring such stock exactly into a predetermined position relative to said second mentioned 65 punch, and a normally ineffective stop mech-

anism operative when the stock is inaccurately positioned.

103. A machine of the nature disclosed comprising, in combination, a main frame, a subframe supported by said main frame 70 and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other 75 end of the machine, a device adapted to advance into engagement with the stock to withdraw the same from said conveyer, a mechanism movable transversely to said device adapted to receive and accurately position the stock carried thereby, and a normally ineffective stop mechanism operative 80 when the stock is inaccurately positioned.

104. A machine of the nature disclosed comprising, in combination, a main frame, a subframe supported by said main frame 90 and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end 95 of the machine, a device having a pair of spring-tongs adapted to be reciprocated toward the end of said conveyer to enable said tongs to frictionally engage the stock therein, means for coöperating with said device whereby the stock may be successively removed from said conveyer and accurately positioned relative to said second mentioned punch, and a normally ineffective stop mechanism operative when the stock is inaccurately positioned.

105. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring-fingers mounted opposite the end of said conveyer and adapted to reciprocate toward the same, means operative to reciprocate said device to enable the latter to successively withdraw stock from said conveyer, a mechanism adapted to receive the stock from said device and accurately posi- 110 115 120 125 130

- tion the same relative to said second mentioned punch, and a normally ineffective stop mechanism operative when the stock is inaccurately positioned.
- 5 106. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to advance 10 into engagement with the stock to remove the same from said conveyer, a plunger for forcing the stock from said device, a spring normally maintaining said plunger in its retracted position, means operative against the resistance of said spring adapted to reciprocate said plunger to force the stock from said device, a mechanism adapted to receive the stock and accurately position the same relative to said second mentioned 15 punch, and a normally ineffective stop mechanism operative when the stock is inaccurately positioned.
- 20 107. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device having a pair of spring tongs adapted to be reciprocated toward the end of said conveyer to enable said tongs to frictionally engage the stock, means for operating said device whereby the stock may be successively withdrawn from the end of said conveyer, a mechanism movable transversely to said device adapted to receive the stock carried thereby, means co-operating with said mechanism for accurately positioning the stock relative to said second mentioned punch, and a normally ineffective stop mechanism operative when the stock is inaccurately positioned.
- 25 108. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer adapted to reciprocate toward the same, a plunger, a spring maintaining said plunger in a normal position, means operative against the resistance of said spring adapted to reciprocate said plun- 30 35 40 45 50 55 60 65 70 75 80 85 90 95 100 105 110 115 120 125 130

ger to enable the latter to discharge stock from said device, a mechanism movable transversely to said device to receive the stock discharged therefrom, a second mechanism co-operating with said first mentioned mechanism for receiving the stock from the former and positioning the same, means for actuating said second mechanism, and a normally ineffective stop mechanism operative when the stock is inaccurately positioned.

111. A machine of the nature disclosed, comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device comprising a pair of spring fingers mounted opposite the end of said conveyer and adapted to advance into engagement with stock carried thereby to remove the same, a plunger, a spring normally retaining said plunger in its retracted position, means operative against the resistance of said spring adapted to reciprocate said plunger, mechanism movable transversely to said device adapted to receive the stock discharged by said plunger, means co-operating with said mechanism for accurately positioning the blanks relative to said second mentioned punch, and a normally ineffective stop mechanism operative when the stock is inaccurately positioned.

112. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be preformed thereby during an advance reciprocation of one of said parts, means for conveying the pre-formed stock to the other end of the machine, a device comprising a pair of spring fingers mounted opposite the ends of said conveyer adapted to reciprocate in alignment with said conveyer, a plunger, a spring normally maintaining said plunger retracted relative to said fingers, intermittent means operative against the resistance of said spring adapted to advance said plunger, mechanism movable transversely to said device adapted to receive stock discharged by said plunger, a second mechanism co-operating with said first-mentioned mechanism for accurately positioning the stock relative to

said second mentioned punch, and a normally ineffective stop mechanism operative when the stock is inaccurately positioned.

113. A machine of the nature disclosed comprising, in combination, a main frame, a subframe supported by said main frame and adapted to reciprocate thereon, a punch carried at the end of one of said parts, another punch carried at the other end of one of said parts, means for conveying stock into operative relation with said first mentioned punch to enable said stock to be pre-formed thereby during an advance reciprocation of one of said parts, means for conveying the pre-formed stock to the other end of the machine, a device having a pair of spring tongs adapted to be reciprocated toward the end of said conveyer to enable said tongs to frictionally engage stock, means for operating said device whereby the stock may be successively withdrawn from the end of said conveyer, a mechanism comprising a pair of spring tongs arranged transversely to said first mentioned tongs and adapted to receive the stock carried thereby, means for reciprocating said mechanism transversely to the movement of said device, a roulette for receiving the stock from said mechanism and for bringing the same into a succession of predetermined positions, and a normally ineffective stop mechanism operative when the stock is inaccurately positioned.

114. A machine of the nature disclosed, comprising, in combination, a main frame, a sub-frame supported by said main frame and adapted to reciprocate thereon, a punch carried at the end of one of said parts, another punch carried at the other end of said part means for conveying stock into a position enabling the first-mentioned punch to perform the same during an advance reciprocation of one of said parts, a pair of members adapted to abut opposite sides of the stock to accurately position the same in registry with said punch, pivoted arms supporting said members, means for simultaneously causing each of said members to approach the other, whereby each will be equidistant from a common center line, and means for conveying the pre-formed stock to the other end of the machine in operative relation with the second-mentioned punch to enable the latter to further operate on said stock during a return reciprocation of said part.

115. A machine of the nature disclosed comprising, in combination, a main frame, a subframe reciprocally carried thereby, a metal working implement carried at each end of said sub-frame, means for continuously interposing stock into operative relation with each of said implements, whereby both the advance and return reciprocations of said sub-frame may be effectively utilized, and stock centering mechanism for accu-

rately registering the stock with one of said implements.

116. A machine of the nature disclosed comprising, in combination, a main frame, a sub-frame reciprocally carried thereby, a metal working implement carried at each end of said sub-frame, means for continuously interposing stock into operative relation with each of said implements whereby 10 both the advance and return reciprocations of said sub-frame may be effectively utilized, stock-centering means comprising two members adapted to be brought into abutment with the sides of the stock to center the same, arms supporting said members and restricting the direction of movement thereof, and cam means simultaneously co-acting with said arms adapted to positively move the same to equispace said members from a 20 common center line.

117. A machine of the nature disclosed comprising, in combination, a main frame, a sub-frame reciprocally carried thereby, a metal working implement arranged adjacent each end of said sub-frame, means for interposing stock in the path of one of said implements at one end of said sub-frame, a stock-centering mechanism located adjacent said implement and comprising a pair of 30 arms each pivotally secured to a base, a bar-centering finger carried by each of said arms, an actuating finger carried by each of said arms, a cam simultaneously co-operating with each of said actuating fingers to oscillate said centering fingers to position said stock in registry with said implement, and means for carrying said stock after being preliminarily formed to the other end of said sub-frame for further operations, whereby both 40 forward and return reciprocations of said sub-frame may be effectively utilized.

118. A machine of the nature disclosed comprising, in combination, a main frame, a sub-frame reciprocally carried thereby, a metal working implement arranged adjacent each end of said sub-frame, means for feeding stock into operative relation with the implement at one end of said sub-frame, a stock-centering device comprising a pair of 50 arms each pivoted at an intermediate point to a common base, a centering finger carried by each arm on the same side of its pivot and terminating opposite one another, an actuating finger carried by each of said arms on the other side of said pivot and terminating opposite one another, a cam intervening between said fingers and movable to simultaneously actuate the same, and means comprising a reversely curved track 60 adapted to receive said pre-formed stock and convey the same to the other end of said sub-frame, whereby the implement at such end may further operate on said stock.

119. A machine of the nature disclosed comprising, in combination, a main frame,

a sub-frame reciprocally carried thereby, a punch mounted on one end of said sub-frame, a die mounted on the adjacent part of the main frame in registry with said punch, means for interposing stock between said punch and die to enable said punch to operate thereon, stock-centering mechanism comprising a pair of arms terminating adjacent the path of said punch and each pivoted at an intermediate point to a common base, a centering finger carried by each arm on the same side of its pivot and terminating adjacent the path of said punch, an actuating finger carried by each of said arms on the other side of its pivot and terminating adjacent one another, a cam intervening between said fingers and movable to simultaneously actuate the same, a trackway for receiving the stock pre-formed by said punch and adapted to convey the same to the 85 other end of the sub-frame, an implement mounted adjacent the other end of said sub-frame, and means for receiving the stock from said trackway and positioning the same in suitable registry with said implement, whereby the same may operate during a return reciprocation of said sub-frame.

120. A machine of the nature disclosed comprising, in combination, a main frame, a sub-frame reciprocally carried thereby, a punch mounted on one end of said sub-frame, a die mounted on an adjacent part of said main frame in registry with said punch, means for introducing the end of a stock-bar between said punch and die to enable 100 portions to be sheared into said die, a bar-centering mechanism comprising a pair of arms each pivoted at an intermediate point to a common base, a centering finger carried by each arm on the same side of its pivot and terminating adjacent opposite sides of the stock-bar, an actuating finger carried by each of said arms on the other side of its pivot and terminating opposite one another, a two-part wedge-shaped cam adapted 105 to reciprocally translate between said actuating fingers to simultaneously actuate the same, a trackway adapted to receive blanks from the open end of said die curving reversely in direction toward the other end of said sub-frame and adapted to convey the blanks to said end, a punch mounted on the other end of said sub-frame, a second die mounted on an adjacent part of the main frame, and means for receiving the blanks 110 from said trackway and interposing the same between the punch and die to enable the former to further operate on said blanks.

121. A machine of the nature disclosed comprising, in combination, a main frame, a sub-frame reciprocally carried thereby, a punch mounted on the end of said sub-frame, a die mounted on an adjacent part of the main frame in registry with said punch, a feedway for a stock-bar leading to- 125 130

ward said die, means for feeding a stock-bar through said feedway into the path of said punch to enable the same to shear blanks therefrom during a forward reciprocation of said sub-frame, a bar-centering mechanism comprising a pair of arms each pivoted above and below said feedway and having parts extending over said feedway, a centering finger carried by each of said arms and terminating respectively above and below said feedway in longitudinal registry therewith, means arranged at one side of said feedway coöoperating with portions of said arms to actuate said centering fingers, a channel leading toward the end of the main frame adapted to convey the blanks sheared by said punch, an open frame trackway consisting of a plurality of track members arranged equidistant from one another and from a common axis, said trackway having one end secured to the main frame to receive the nut blanks and reversely curving with its other end directed toward the opposite end of the machine, a straight line trackway connected with the delivery end of said curved open frame trackway and leading to a point adjacent the other end of said sub-frame, a metal working implement mounted adjacent the last-mentioned end of said sub-frame, and means for receiving stock from said straight line trackway and interposing the same in the path of said implement.

122. A machine of the nature disclosed comprising, in combination, a die, a punch, means adapted to cause relative movement between said parts to effect punching, means adapted to feed stock into position to be operated on by said die and punch, means adapted to accurately register the portion of said stock to be punched relative to said die and punch, means adapted to clamp in punching position the portion of the stock to be punched, means adapted to relieve the clamping effect of said clamping means after the punching has been accomplished, means adapted to receive and support the punched blanks in predetermined order, means adapted to remove a blank from said supporting means and dispose the axis of the removed blank in predetermined position, and means adapted to receive and hold blanks delivered from said removing means.

123. A machine of the nature disclosed comprising, in combination, a die, a punch, means adapted to cause relative movement between said parts to effect punching, means adapted to feed stock into position to be operated on by said die and punch, means adapted to accurately register the portion of said stock to be punched relative to said die and punch, means adapted to clamp in punching position the portion of the stock to be punched, means adapted to relieve the clamping effect of said clamping means

after the punching has been accomplished, means adapted to receive and support the punched blanks in predetermined order, means adapted to remove a blank from said supporting means and dispose the axis of the removed blank in predetermined position, means adapted to receive and hold blanks delivered from said removing means, and means adapted to transfer blanks from said removing means to said receiving and holding means and into predetermined relation to said latter means.

124. A machine of the nature disclosed comprising, in combination, a die, a punch, means adapted to cause relative movement between said parts to effect punching, means adapted to feed stock into position to be operated on by said die and punch, means adapted to accurately register the portion of said stock to be punched relative to said die and punch, means adapted to clamp in punching position the portion of the stock to be punched, means adapted to relieve the clamping effect of said clamping means after the punching has been accomplished, means adapted to receive and support the punched blanks in predetermined order, means adapted to remove a blank from said supporting means and dispose the axis of the removed blank in predetermined position, means adapted to receive and hold blanks delivered from said removing means, means adapted to transfer blanks from said removing means to said receiving and holding means and into predetermined relation to said latter means.

125. A machine of the nature disclosed comprising, in combination, a die, a punch, means adapted to cause relative movement between said parts to effect punching, means adapted to feed stock into position to be operated on by said die and punch, means adapted to accurately register the portion of said stock to be punched relative to said die and punch, means adapted to clamp in punching position the portion of the stock to be punched, means adapted to relieve the clamping effect of said clamping means after the punching has been accomplished, means adapted to receive and support the punched blanks in predetermined order, means adapted to remove a blank from said supporting means and dispose the axis of the removed blank in predetermined position, means adapted to receive and hold blanks delivered from said removing means, means adapted to transfer blanks from said removing means to said receiving and holding means and into predetermined relation to said latter means, a second punch, a second die coöperatively associated with said second punch, and means adapted to receive blanks from said receiving and holding means and carry same into operative register with said second die and punch.

126. A machine of the nature disclosed comprising, in combination, a die, a punch, means adapted to cause relative movement between said parts to effect punching, means adapted to feed stock into position to be operated on by said die and punch, means adapted to accurately register the portion of said stock to be punched relative to said die and punch, means adapted to clamp in punching position the portion of the stock to be punched, means adapted to relieve the clamping effect of said clamping means after the punching has been accomplished, means adapted to receive and support the punched blanks in predetermined order, means adapted to remove a blank from said supporting means and dispose the axis of the removed blank in predetermined position, means adapted to receive and hold blanks delivered from said removing means, means adapted to transfer blanks from said removing means to said receiving and holding means and into predetermined relation to said latter means, a second punch, a sec-

ond die coöperatively associated with said second punch, means adapted to receive blanks from said receiving and holding means and carry same into operative register with said second die and punch, means adapted to move said receiving and holding means into receiving position relative to said removing means and into delivery position relative to said receiving and carrying means, and means adapted to transfer blanks from said receiving and holding

means to said receiving and carrying means, and dispose the axes of said respective blanks in predetermined position.

In testimony whereof we affix our signatures in the presence of two witnesses.

WILLIAM L. WARD.
EMILE C. BOERNER.
HERBERT D. REMSEN.
